UNITED STATES PATENT OFFICE

CHARLES V. KISSINGER, OF TULSA, OKLAHOMA, ASSIGNOR OF TWENTY PER CENT TO ROBERT J. BARRITT AND TWENTY PER CENT TO ARCHIE S. SANDS, BOTH OF PAWHUSKA, OKLAHOMA, AND TWENTY PER CENT TO LOUISE V. YOUNG, OF TULSA, OKLAHOMA

RECORD-HANDLING MECHANISM FOR PHONOGRAHS

Application filed September 19, 1928. Serial No. 306,791.

This invention relates to phonographs and has special reference to a record handling mechanism for phonographs constructed and arranged to perform all of the acts usually

5 performed by a person when using a phonograph, the mechanism being accordingly so constructed and arranged as to remove from a rack a selected record, place it on the turn table of the phonograph with the desired side

10 uppermost, place the reproducer and its needle in position, start and maintain the table in rotation, stop the table automatically at the end of the record or at any time between the start and finish of the record at the will

15 of the operator, and upon stopping of the playing of such record automatically perform anyone of the following operations; first, remove the record and replace it in its proper position in the cabinet; second, remove the

20 record, turn it over and present it with its other side up and effect playing of the last mentioned side as before; third, repeat the playing of the record last played without replacing the record in the cabinet; and, fourth,

25 cause one side or both sides of one or more records to be played in succession to that first played without further intervention or manipulation by the operator.

One important object of the invention is to 30 provide an improved device of this description wherein all of the operations above referred to may be controlled at any desired distance from the phonograph and record cabinet or racks.

35 A second important object of the invention is to provide an improved device of this description wherein a series of records are held in a record cabinet, a selector moves past the series of records and stops in proper relation to a selected record and an elevator moves into position to grip the selected record and then moves to withdraw the record, being guided by the selector in its motion.

40 A third important object of the invention is to provide, in a machine of this description, a selector as above set forth which is so arranged that it remains set in its selected position during the entire operation of withdrawing the record, playing the record either on

50 one or both sides, and returning the record to

its proper position in the cabinet or rack, the selector thus preventing misplacement of a record in returning the same.

A fourth important object of the invention is to provide, in a machine of this description, 55 a pair of record racks each holding a series of records and a selector and elevator operating between the pair of racks in the manner aforesaid, the selector carrying means whereby the elevator is guided into position to withdraw 60 and return a selected record from a selected rack of said pair.

A fifth important object of the invention is to provide, in a machine of this class, an elevator adapted to withdraw and return a selected record from a record rack and to move 65 the same to such position as to bring a selected side of the record uppermost when placed upon the phonograph turn table.

A sixth important object of the invention 70 is to provide, in a machine of this class, an elevator for gripping and withdrawing a record from a record rack, means to move said elevator and cause it to present a selected side of the record uppermost and a carrier for receiving the record from the elevator and depositing it on the turn table.

A seventh important object of the invention is to provide, in a machine of this class, a 75 carrier and elevator and operative means for the carrier and elevator so arranged that the carrier will be caused to remove a record from the turn table of the phonograph, present the record to the elevator, the elevator being caused to move in such manner as to reverse 80 the record and present the side which was previously beneath in an uppermost position and the carrier finally to take the newly presented record and replace it on the turn table.

An eighth important object of the invention 85 is to provide, in a machine of the class described, novel and improved means whereby a record may be repeatedly played.

A ninth important object of the invention 90 is to provide, in a machine of the class described, a selector, elevator and carrier operating in combination with a record rack holding a series of records and controlling and operating means for the selector, elevator and carrier so arranged that they may be caused 95 100

to successively withdraw, play one or both sides and return to position a series of phonograph records.

A tenth important object of the invention is to provide means whereby all of the operations aforesaid may be electromagnetically controlled from one or more remote points at the will of the operator.

An eleventh important object of the invention is to provide means, in a device of the kind described, of novel and improved character whereby, after the completion of the desired operation or cycle of operations the various parts of the mechanism are restored 15 to normal position automatically and without intervention on the part of the operator.

A twelfth important object of the invention is to provide means for signalling at the operator's station conditions existing in the 20 mechanism of the phonograph.

A thirteenth important object of the invention is to provide novel means whereby, in the event of the failure of the carrier to place a record on the turn table from any cause 25 such as the operator selecting a record to be played which had been removed manually from its place in the rack whereby the elevator and carrier would function empty, the further operations of the parts usual in normal playing of the record will cease and all 30 parts be restored to their normal positions.

A fourteenth important object of the invention is to provide a machine of this character wherein any record may be removed from the 35 machine and its space left blank or a second record substituted therefor without disturbing any of the remaining records, or interfering with the operation of the machine on such remaining records.

A fifteenth important object of the invention is to provide means whereby, during the actual playing of a record, all of the mechanism of the attachment will remain quiescent so that the playing of the record is not interfered with by the operation of the handling 45 mechanism, the playing of the record not starting until all of the handling mechanism and its motive means have come to rest.

A sixteenth important object of the invention is to provide means whereby if a wrong 50 number be dialed the parts may be automatically returned to normal.

A seventeenth important object of the invention is to provide means whereby the volume 55 control mechanism of a phonograph or the like instrument may be itself controlled from a remote point by manipulation of the dial.

An eighteenth important object of the invention is to provide means whereby corrections or changes in a dialed number may be 60 effected by the operation of an emergency circuit.

With the above and other objects in view 65 as will be hereinafter apparent, the inven-

tion consists in general of certain novel details of construction and combinations of parts hereinafter fully described, illustrated in the accompanying drawings and specifically claimed.

In the accompanying drawings like characters of reference indicate like parts in the several views, and:

Figure 1A is a plan view of the mechanism at the upper part of the device and at the 75 left hand side of the machine, certain of the parts below being omitted to avoid confusion.

- Figure 60 is a detail of the switch of Figure 59 with the parts in a third position;
- Figure 61 is a detail showing the latching 110 rods for the record selector;
- Figure 62 is a view of certain parts of the turn table starting device;
- Figure 63 is a view of certain switches controlled by the position of the sound arm;
- Figure 64 is a view in elevation of certain 120 parts used in replacing the tone arm in its position of rest;
- Figure 65 is a view of certain parts in elevation of certain parts for cooperating with 130

those shown in Figure 64 to move the tone arm from rest to playing position.

Figure 66A, B and C show the several parts of wiring diagram of the mechanism.

It is thought best to describe in general the various operations of the main features of the invention before entering into any detailed description of the construction and means whereby such main features are caused to operate. To this end it will be noted that the machine is provided with a pair of vertical record racks R and R', and guided to move vertically between these racks is a selector A having at its top a guiding element B. Likewise between the racks above the selector is positioned an elevator C which moves in a general vertical direction between the racks R and R' and may be caused to travel along one or the other of the Y branches of the track D by means of a switch E and thus be brought in parallel position with either side uppermost below a horizontally movable carrier F so that the carrier may receive and transport a record Re to the turn table G of the phonograph. A control device H having a dial such as is used in ordinary telephone systems at the subscriber's instruments, is connected electrically to the apparatus by a cable I.

Now, let it be supposed that it is desired merely to play a selected side of a selected record and after the record is played to restore the same to its position in the rack. Either rack space is given a three number designation, the first number corresponding to the rack and "1" for the left hand rack and "3" for the right hand rack of one side of each record in said racks and, say, "2" for the left hand rack and "4" for the right hand rack of the other side. The second and third numbers relate solely to the positions of the records in the racks and for the purposes of this machine the figure zero is omitted. Thus the first record in the left hand rack will have the numbers "111" and "211" assigned to the respective sides. Similarly, the second record in that rack will have the numbers "112" and "212" to its respective sides. The ninth record will have its sides numbered "119" and "219" respectively while the tenth record will have its sides numbered "121" and "221" respectively. It is important that this be borne in mind to understand the operation in its details as will be hereinafter set forth. Now, suppose it is wished to play one side of a record designated as "119". The dial is manipulated just as though a person was going to call a telephone bearing that number. Upon the completion of the dialing the motive mechanism of the device starts and the selector and elevator move upwardly together to a point slightly above that at which the selector should be positioned to guide the elevator in its movement to grip the record. The selector then drops back

a slight distance to its proper position and is locked in that position during the remainder of the operation. At the same time the guide B on the selector is regulated in position to direct the elevator in its downward movement toward the proper rack R. At this instant the motion of the elevator is reversed and it descends, being guided by the selector, to such position that it may grasp the edge of the selected record which it does. Its motion is again reversed and it travels upward into the proper branch of the Y to present the record face "119" uppermost. The motion of the elevator now stops and the carrier grasps the record, frees it from the elevator, raises it, transports it laterally to a position over the turn table and releases it. The carrier now moves backwardly to a point intermediate its travel but where it will be free from the record and at this time the reproducer engages the record and when the carrier has stopped in its movement and the motive means for the attachment has come to rest the motor of the phonograph is cut in and the turn table revolves and the record is played. Upon completion of the playing of the record the turn table motor is cut out and the motive means for the carrier and other parts of the attachment is cut in. The carrier now moves to a position over the record on the turn table and at this time the reproducer is lifted free of the record and restored to its normal or idle position by the carrier. The carrier now grasps the record and moves backwardly into position to deliver the record to the elevator which grasps the record which is now released by the carrier and the elevator moves along the Y track and downwardly until it engages the selector which guides it so that the record is restored to its proper place in the rack whereupon the elevator releases the record. The elevator then rises until it alines vertically with the selector which, at this time, is released and the elevator and selector descend together to their lowermost positions which, being reached, the motive means of the device cut out and all parts come to rest, the carrier having meantime assumed its normal position.

Suppose now it be desired to repeat the playing of the record which has just been played. Before the record is picked off the turn table by the carrier a circuit, which may be called the repeat circuit, is closed by pressing a button in the dial box. The action will now be the same as before up to the point at which the carrier moves forward the second time to pick up the record from the turn table. From that point on the following operation takes place.

The carrier picks up the record, moves back to a position ready to lower the record so that it may be grasped by the elevator grips. It does not, however, lower this record

but simply pauses momentarily, reverses and replaces the record on the turn table and then moves to the intermediate position at which it rests while the record is played. Unless the repeat button be again pressed the operation of putting the record back in the rack will be carried out after the playing is finished.

It may be desired to play one side of the record and then the other without putting it away and thus necessitating redialing. To accomplish this the dialing for one side is performed as before and the record carried and placed with the first side to be played uppermost on the turn table. This side is then played and the carrier moves as before to remove the record and deliver it to the elevator. The elevator grasps the record and starts downwardly just as though the record was to be restored to its rack but when the elevator has passed below the junction of the arms of the Y the switch on the Y automatically shifts, the elevator reverses and moves upwardly in the other branch of the Y and thereby brings the second side of the record uppermost. The carrier now operates to take the record from the elevator and place it on the turn table as before whereupon the carrier moves to its intermediate rest position, the record is played and the carrier and elevator operate to restore the record to the rack as in the first instance.

It may be desired to play records from the rack in succession without redialing and to accomplish this a button in the dialing box governing what may be termed the consecutive circuit is pushed to close such circuit. The dialing of the first number of those to be played is now performed whereupon the first of the series of records will be removed from the rack, played and replaced just as though a single record was to be played exactly as described above in such case. However, at the completion of the replacement of this record the selector does not descend to its normal position and there stop but on the contrary the selector moves to position for selection of the next record from the rack and the elevator and carrier go through the usual operations incident to withdrawing, playing and returning such record. Unless the operator interferes the records in the rack will be played one after the other until the last record is reached whereupon all parts will resume their normal, inactive positions after the playing of this last record and operation will cease.

It is here to be noted that a special emergency circuit is provided by means of which, during the playing of any record, the operation of the parts to remove the record from the turn table and restore it to the rack may be accomplished. This circuit is controlled by an emergency button in the dial box and should it be desired to stop the playing of a

record or to stop the consecutive operation in playing consecutive records the operator simply pushes this button. Thereupon the record on the turn table is at once removed through the usual operation of the carrier and elevator and restored to its position in the rack after which the parts move to their normal inoperative positions and the motor stops.

It may also be desirable not only to play one side of a series of records consecutively but to play first one and then the other side of each of a series of records in succession without operative intervention. In such case the consecutive circuit is closed, the dialing performed for the first of the series of records and the record reversing circuit then closed. Under these circumstances there will be a combination of the consecutive operation and the reversing operation so that between consecutive withdrawals of the series of records the reversing operation above described for a single record will be performed and any one may be repeated as heretofore described.

Should an error have been made in dialing first or second digit the pressing of a button at the box which is termed the emergency button will return all parts to normal position causing the white light in all remote controls to appear indicating machine is clear ready for dialing again.

Should operator have changed his mind regarding particular side of record or particular record dialed he may correct by pressing emergency button. If record has not been withdrawn by elevator the mechanism will proceed up past the rack and return to normal position. If the record has been withdrawn it will be caused to return at a point just before being transferred to carrier and caused to be returned to its proper place in the rack then the mechanism of machine will return to its normal position.

The different operations of which the mechanism is capable have now been generally described and the specific structure by means of which these operations are carried out will be described in detail.

Dial box

The dial box used with this device includes a casing 10 wherein is supported a plate 11 preferably formed of insulating material. Mounted on this plate is a dialing device 12 having at the back of the plate a circuit closing and opening cam 13 which is geared to the main shaft 14 of the dialing device in the ordinary manner common to such devices. The present dial and gearing being that disclosed in the catalog of The Automatic Electric Company of Chicago, Illinois, and sold under their stock number D84702A. Fixed to this shaft 14 is an arm 15 which carries a dog 16. Mounted between insulating blocks 130

17 is a spring contact member 18 which is held normally in contact with a second spring contact member 19 by means of an arm 20 carried by the shaft 14. This second contact member 19 is supported on one side of the pair of blocks 17 and its free end bears against the cam 13. The contact members 18 and 19 are both spring members and are so arranged that their spring action constantly urges them towards a fixed contact member 21 which is in the form of a stiff metal bar. Mounted on opposite sides of an insulating block 22 is a pair of spring contact members 23 and 24 which are normally separated.

15 The plate 11 is provided with three openings wherein are set bull's-eye glasses, there being preferably a white bull's-eye 25, a red bull's-eye 26 and a green bull's-eye 27. In the casing behind these bull's-eyes are the respective lamps for throwing light through the bull's-eyes in accordance with the selective closing of certain circuits as will be hereinafter described. While these lamps are all of the usual construction and not colored 20 they will be referred to for the purposes of description as though they had the same colors as the bull's-eyes. That is to say, the lamp 28 behind the white bull's-eye will be called the white lamp and in like manner the lamp 29 will be the red lamp and lamp 30 the green lamp.

16 Mounted on the plate 11 is a manually operable double pole switch 31 having the movable contact members 32 and 33. The arm 32 normally lies spaced from the fixed contact 34 while the arm 33 is similarly spaced from the fixed contact 35 but this latter arm normally engages a further fixed contact 36. There are also provided and mounted on the plate 11 a series of double pole circuit closers or push buttons each having certain peculiar functions in connection with definite circuits. These buttons are shown as follows. At 37 is a button which I preferably term the error and emergency button. At 38 is a button termed the volume control button. At 39 is the consecutive and record reversing button while at 40 is the repeating button. Positioned along the side of the dial box is a 50 series of binding posts or terminals thirteen in number and numbered consecutively from 41 to 53. The wiring within the box is arranged as follows. The contacts 21 and 23 are connected by a wire 54 from which extends a wire 55 which leads to the contact 35. From the contact 19 extends a wire 56 which leads to the binding post 43. From the contact 24 a wire 57 leads to the binding post 44. From the contact 34 a wire 58 leads to the binding post 53. From the movable contact 32 a wire 59 leads to the binding post 52, these two binding posts being the positive and negative posts of a motor operating circuit preferably of 110 volts. From the movable contact or arm 33 a wire 60 leads to a

wire 61 which is connected by a wire 62 with the binding post 45. From each of the switches 37, 38, 39 and 40 leads a wire 63 which connects with the wire 61 so that one side of each of these push buttons or switches is connected to the binding post 45. The opposite side of the push button 37 is connected directly through a wire 64 to the binding post 46. The opposite side of the push button 38 and the contact 36 are connected in multiple by a wire 65 to the binding post 47. The opposite side of the push button 39 is connected by a wire 66 to the binding post 42 and the opposite side of the push button 40 is connected by a wire 67 to the binding post 41. Finally one side of the green light 30 is connected by a wire 68 to the wire 61 and the other side is connected by a wire 69 to the binding post 51. This completes the connections of the parts in the dial box. A 110 volt current is received through the mains 70 and 71, the latter being connected directly to the binding post 52 while the main 70 is provided with a branch 72 which connects to one intake terminal of a battery charger 73 having its other intake terminal connected by a wire 74 with the binding post 53. The wire 70 is also connected to one terminal of a transformer primary 75 which has its other terminal connected by a wire 76 to the wire 74. The secondary 75' of this transformer has one terminal connected to a movable contact 77 of a switch while its other terminal is connected by a wire 78 to the binding post 50 to which the white and red lights 28 and 29 are connected in multiple through a wire 79. The other sides of these lights being connected by respective wires 80 and 81 with the binding posts 49 and 48 which are in turn connected by wires 82 and 83 with fixed contacts 84 and 85 between which the arm 77 moves, said arm being normally in contact with the contact 84. The circuit through the white and red lights is thus stepped down from 110 to 8 volts.

At 86 on the base of the instrument is located a storage battery having a potential of preferably 12 volts. The terminals of this battery are connected by wires 87 to the output terminals of the charger 73 and the negative terminal of the battery 86 is connected by a wire 88 to the binding post 45.

The main structure

In the main structure of the device there is 120 provided a base 89 which supports at one end a suitable steel frame 90 properly arranged to carry the various parts and it is not deemed necessary to specifically describe the several elements making up this frame inasmuch as 125 the structure of the frame itself forms no particular part of this invention. On the other end of the platform 89 is supported a phonograph or other sound reproducing instrument 91 which may be of any preferred 130

type but which is provided with a driving motor, the circuit of which is closed through a switch (not shown) of the type common in such instruments. The motor, the gearing driving the turn table 431 from the motor and the switch arrangements for supplying current to and cutting off the current from the motor are all of well known and standard construction and the details of these parts 5 are accordingly omitted both in the showing and in the description of the invention since no claim is made to any particular motor drive, gearing or switch means other than the fact that the lever 92 cooperates or has connected thereto certain parts of the invention 10 which are affected by the operation of such lever in turning the current on or off of what will be termed the phonograph motor. The 15 battery and charger are mounted on the base 20 which supports the phonograph and the frame.

The motor and drive

Supported by the frame 90 is a shelf or 25 platform 94 beneath which is suspended the driving motor 95, the rotor shaft of which is geared by worm gearing 96 to a vertical shaft 97 which extends up through the said shelf 94 and carries on its upper end a gear 98 which meshes with a gear 99 carried by a vertical shaft 100 which runs down through the shelf 94. This shaft 100 carries on its upper end a gear 101 which meshes with a gear 102 fixed on a vertical shaft 103 which 30 extends substantially to the top of the machine for purposes hereinafter to be described. On the lower end of the shaft 100 is a bevel gear 104 on one side of which meshes a bevel gear 105 which is fixed on a shaft 106. On the shaft 106 is a revoluble 35 clutch member 107 and splined to said shaft is a sliding clutch member 108 which is operated by a bellcrank shipper 109 having a horizontal arm which extends below a magnet 110 and forms the armature therefor. Alined with the shaft 106 is a similar shaft 111 meshing, by means of a bevel gear 112, with the gear 104 and this shaft likewise 40 carries a loose clutch member 113 and a splined clutch member 114 operated by a shipper fork 115 which is connected to the fork 109 by a link 116. Each revoluble clutch member carries a gear 117 which meshes with 45 one of a pair of gears 118 fixed on a shaft 119 carrying at its ends sprockets 120 for driving the elevator chains 121. The motor is provided with the usual governor 122 of ordinary construction. The shipper 115 is provided with a horizontal arm which extends 50 beneath the magnet 123 to form the armature therefor. Now, it will be obvious that if magnet 110 is energized the clutch member 108 will be engaged and the member 114 disengaged and the reverse will take place when 55 the magnet 123 is energized. It will also be

obvious that rotation of the motor 95 will, through the gears 98 and 99, drive the shaft 100 and they in turn through the gears 104, 105 and 112 will drive the shaft 106 and 111 and that if one of the clutch members 108 or 114 be engaged the corresponding gear 118 will be rotated so that, depending on which clutch member is engaged, the shaft 119 will rotate in one direction or the other. 70

One brush of the motor is connected by a wire 124 with the wire 74 while the other brush of the motor is connected by a wire 125 with one movable arm 126 of a double pole switch preferably of the mercury type. This arm 126 normally lies free from a contact 127 which is connected by a wire 128 with the wire 70. A wire 129 connects the other movable arm 130 of this switch with the wire 124 and the switch is provided with a second switch contact 131 which is connected by a wire 132 with the wire 71, this fixed contact being normally free from the contact 130. A magnet 133 is used to close this mercury switch, this switch being located on a shelf or platform 134 above the shelf 94. One 90 terminal of this magnet is connected by a wire 135 to a magnet 136 to which the arm 77 forms the armature, the magnet 136 being in turn connected by a wire 137 to the wire 88. The other terminal of the magnet 133 is connected by a wire 138 to a normally closed switch 139, the operation and construction of which will be hereinafter described. This switch is in turn connected by a wire 140 to the negative side of the battery 86 but between the two magnets 136 and 133 a wire 141 is connected to the wire 135, this wire receiving positive current as will be hereinafter described. 95 100

Automatic selector units

Mounted on suitable shelves or supports are certain automatic selector units 142 which, for convenience are distinguished by the affixed letters "a" to "f", there being six of these 110 units. In general these units are alike and certain features of the construction are identical in all while the circuit connections and contacts in each unit differ from the rest. Accordingly those features which are identical 115 will be indicated by identical characters and will be first described after which the parts distinguishing one unit from the others will be set forth.

Each of these units has upper and lower 120 frame plates 143 and 144 which at one end of the unit are held in spaced relation by bolts 145 while the opposite ends are spaced by an insulating plate 146. Rotatably journaled in the plates 143 and 144 is a main shaft 125 147 which is urged to normal position by a coiled spring 148. On the bolts 145 is supported a horizontal insulating plate 149 termed the contact plate and used to support certain fixed contacts which vary in number 130.

and arrangement in the several units. Projecting from the plate 146 is an operating magnet 150, these magnets being severally designated by the letter affixes "a" to "f" as 5 are the units themselves. Similarly, each unit has a release magnet 151 each distinguished by the same literal affixes. On a pivot shaft 152 is mounted an operating lever 153 carrying at one end a spring pawl 154 and at the 10 other end an armature 155 for the magnet 150. On a bracket 156 is mounted a latching pawl 157 also of spring material. Mounted on the shaft 158 is a release lever 159 which carries an armature 160 acted upon by the 15 magnet 151 at one end and at its other end has a finger 161 which lies behind the spring pawls 154 and 157 so that energization of the magnet 151 moves both pawls. These pawls operate on a ratchet 162, the ratchets 20 for the several units being distinguished by literal suffixes as before. Each shaft is provided with a stop device 162' for stopping the shaft in normal position.

Considering now the first unit or unit 142a. 25 On the insulating plate 149 is mounted a set of four spaced contacts 163; a second set of contacts consisting of a point contact 164 and a long contact strip 165 the length of which is equivalent to the space occupied by 30 three of the contacts 163; and finally a point contact 166. Contact fingers 167, 168 and 169 are carried by the shaft 147 but are insulated from said shaft and from each other, these fingers cooperating respectively with the several groups or sets of contacts and the fingers 35 167 and 168 resting on the first contact 163 and the contact 164 respectively but the finger 169 being free from the contact 166 and only engaging this contact upon the shaft moving 40 to bring finger 167 into engagement with the fourth contact 163.

The next unit has a single set of four contacts 170 and a long arcuate contact 171 equal in length to the space occupied by the four 45 contacts 170. This set of contacts 170 is traversed by a finger 172 and the long contact 171 by a finger 173, the fingers being carried by the shaft but insulated from it and from each other. In this unit the fingers are normally 50 free from the contacts which they traverse.

In unit 142a, which may be termed the "tens" unit, there is a set of contacts 174 which are traversed by the insulating finger 175 and the number of contacts 174 which 55 are used will be governed by the number of records carried by the machine. Thus, in a machine carrying two racks each with nine records but one contact 174 will be used, with eighteen in each rack two will be used, with 60 twenty-seven there will be three and so on for each multiple of nine since all zeros are omitted in dialing.

In unit 142d or the "integer" unit there is a set of nine contacts 176 traversed by an insulated shaft driven finger 177.

In unit 142e there is a single long arcuate contact 178 traversed by a finger 179 and in unit 142f there is a pair of contacts 180 and 181 and a finger 182 which normally rests on the contact 180.

Associated with the unit 142e is a certain switch mechanism. To carry this the unit is provided with a third insulating plate 183 whereon is mounted a magnet 184 having an armature 185 carrying a rod 186 sliding through guides 187. Also mounted on the plate 183 is a pair of contacts 188 and 189 having slightly spaced terminals which are engaged by a contact finger 190 carried by but insulated from the rod 186, the finger normally resting on the contact 188. Opposite this finger the rod carries a single toothed ratchet 191 adapted, upon energization of the magnet 184, to move past and be engaged by a spring pawl 192 which is, upon energization of the magnet 151c, released by a finger 193 attached to the lever 159 of this unit.

It is to be noted that the usual springs will be employed to hold the various armatures and other parts in their normal positions.

Selector unit circuits

By closing the switch 31 a 110 volt circuit will be established from the main 70 through transformer primary 75, wire 76, wire 74, binding post 53, wire 58, contact 34, contact 32, wire 59, binding post 52 and back to the main 71. A shunt circuit through the charger is also established by wires 72 and 76. Now the passage of the current (alternating) through the transformer produces a secondary 8 volt circuit from the secondary 75' through wire 78, binding post 50, wire 79, white light 28, wire 80, binding post 49, wire 82, contact 84, and contact 77 back to the secondary 75'. Thus the white signals "Ready for operation."

For the connection of the selector units and various other parts there extends from the battery 86 a positive lead which has one branch 194 which passes through certain reproducer horn circuit closers (hereinafter to be described) and a second branch 195, the first branch being continued from said circuit closers at 196. The wire 196 leads to one terminal of the magnet 150a and from this magnet a wire 197 leads back to the binding post 44.

The unit 142b has its magnet 150b connected by a wire 198 with the battery positive 196 and the other terminal of said magnet is connected by a wire 199 with the first contact 163 of unit 142a. From the finger 167 a wire 200 leads to the binding post 43. Now, with the operation of the first figure of the dialed number (the hundreds figure) the circuit closing cam 13 will operate to permit engagement of the contact 19 with the contact 21 a number of times corresponding with the number dialed. Each closing of these con-

tacts produces a first dial circuit as follows: battery 86, wire 194, reproducer circuit closers, wire 196, wire 198, magnet 150b, wire 199, first contact 163, finger 167, wire 200, binding post 43, wire 56, contact 19, contact 21, wire 54, wire 55, contact 35, contact 33, wire 60, wire 61, wire 62, binding post 45 and wire 88 back to the battery.

At the end of the dialing of each number through the first dial circuit the dial produces the following result. As each record number is dialed the finger 16 will move freely past the contacts 23 and 24, closing these contacts to produce a second dial circuit on the return to normal. Thus, for each record number these contacts will be closed three times. With each closing of the contacts the second dial circuit is established from the battery 86 through wire 196, magnet 150a, wire 197, binding post 44, wire 57, contact 24, contact 23, wire 54, wire 55, contact 35, contact 33, (the manual switch 31 being closed) wire 60, wire 62, binding post 45, and wire 88 back to the battery.

As the first numeral is dialed the first dial circuit will be closed a number of times corresponding to that numeral. Accordingly the magnet 150b will be energized the same number of times. As will be presently understood these contacts control the selection of the records from the right and left hand racks and the positioning for playing with the one or the other sides uppermost. Normally the apparatus is arranged for selection from the right hand rack and to carry the record around the right hand branch of the Y track so as to present the normal underside up for playing. Accordingly upon dialing any number beginning with the figure "1" no change of the normal positions of the parts controlled by the first circuit of unit 142b is necessary and the first contact 170 is therefore a dead or unconnected contact.

Now if the number dialed begins with the number "2" two impulses will be given the magnet 150b and as a result the finger 172 will move to the second contact 170 from which extends a wire 201 which leads to a certain magnet 202 for shifting the Y switch and from this magnet a wire 203 leads to the positive battery wire 195. Now the finger 172 is connected by a wire 204 with certain mechanism (hereinafter to be described) from which a wire 205 extends back to a battery negative line 206. Consequently if the number dialed begins with "2" there will be a selection of the record from the right hand rack and it will be carried around the left hand branch of the Y track. The third point 170 is connected by a wire 207 to a magnet 208 controlling certain apparatus used for shifting the movement of the elevator to select from the right hand rack and from this magnet a wire 209 leads to the battery positive line 195. Thus if the number begins with "3" and is dialed the apparatus is arranged for selection from the left hand rack and to carry the record around the right hand branch of the Y track. Finally, a wire 210 leads from the fourth contact 170 to a magnet 211, the particular construction of which will be presently described and this magnet controls a normally opened circuit closer embodying a movable contact 212 and a pair of fixed contacts 213 and 214 engaged by the movable contact upon energization of the magnet 211. From the magnet 211 a wire 215 runs back to the wire 209 and thus to the battery positive. From the contact 213 a wire 216 leads to the magnet 208 by connection with the wire 207. From the contact 214 a wire 217 leads to the magnet 202 by connection with the wire 201. From the movable contact 212 a wire 218 leads to certain parts by which it is connected to the wire 205 and thus to the negative side of the battery through wire 140, these parts operating as the selector and elevator start their upward movement. Now, it will be observed that the circuits through the contact 170 are not closed until the selector begins to move upwardly and to this end the selector carries in its movement a lozenge shaped wiper 219 so arranged that in its upward movement it contacts with a spring contact member 220 to which the wires 204 and 218 are connected. Normally the wiper 219 lies below the contacting end of the spring 220 so that until upward movement of the selector takes place the circuits controlled by the finger 172 and contacts 170 will remain open and thus the finger 172 will come to rest upon the proper contact 170 prior to the completion of the required circuit since the action of the finger 172 is completed before the movement of the selector brings the wiper 219 into engagement with the contact 220.

Consequently, upon movement of the finger 172 to the fourth contact 170 both the magnet 202 and the magnet 208 will be energized and the elevator will act for selection of a record from the left hand rack and to carry the record around the left hand branch of the Y track.

Now it will be remembered that the contact 171 of the unit 142b is a long contact so that as the finger 172 passes onto the first contact 170 the finger 173 will engage the contact 171 and will remain in contact therewith throughout the entire operation of the unit 142b. This finger 173 is connected to the battery positive 195 by a wire 221 and the contact 171 is connected to the wire 141 previously described. Now, under these circumstances it will be seen that with the first impulse, that is to say with the first closing of the first dial circuit, a circuit will be established as follows; from the battery 86, through wire 195, wire 221, finger 173, contact 171, wire 141, wire 135 where the circuit branches, one branch passing through magnet 136, wire 130

137 and wire 88 back to the battery negative while the other branch passes through magnet 133, wire 138, circuit closer 139, wire 140, wire 206, back to the battery negative. As a consequence of this the armature or movable contact 77 will break contact with the contact 84 and make contact with the contact 85 so that the white light 28 will be cut out and the red light 29 will be cut in. At the same time the magnet 133 will close the 10 mercury switch and the contacts 126 and 130 will engage the contacts 127 and 131 and thus establish a circuit through the motor 95 and start operation of the motor. Now the 15 circuits just described will continue closed so long as the unit 142b is in service.

It will be remembered that the operation of the magnet 150b only takes place so long as the finger 167 is on the first contact point 163. At this time the finger 168 rests on the 20 contact point 164 and this finger is connected by a wire 222 with the battery positive wire 195. The contact 164 is connected by a wire 223 with the magnet 184 from which passes a wire 185 which leads to the binding post 42. Now no circuit will be closed through this magnet 184 which, as will be hereinafter set forth, controls certain mechanism connected with the reversing of the 25 record so that after one side is played the other side may be played, the magnet also controlling certain mechanism for playing records consecutively.

Now with the first impulse or energization 30 given the magnet 150a by the first closing of the second dial circuit which follows the completion of the dialing of the first numeral, the finger 167 will move to the second contact 163 and the finger 168 will move to the contact 165, the latter finger remaining in 35 engagement with the long contact 165 during the engagement of the finger 167 also with the third and fourth contacts 163. From the second contact 163 a wire 224 leads to the magnet 150c which is the operating magnet 40 for unit 142c. This magnet 150c has its other terminal connected by a wire 225 to the battery positive wire 195. In the dialing operation the second number is now dialed 45 and the first dial circuit is again operated to close and open a number of times corresponding with the numeral dialed. In the present apparatus each rack has been shown with but eighteen records so that, no zeros being 50 used, the number dialed will have for its second numeral or figure either "1" or "2". Obviously, with the addition of other records the second numeral of the number will be correspondingly increased. Now normally 55 the finger 178 is free from the contacts 174 but if the number dialed has for its second numeral "1" the contact 178 will move into engagement with the first contact 174 which is connected by a wire 226 with a group of 60 nine contact points 227, these points being

connected in multiple to said wire. These points correspond to all numbers of which the second numeral is "1". In like manner the second contact point 174 is connected by a wire 228 with a second group of contact points 229 which correspond to the numbers having "2" as their second numeral. The dialing of the second numeral therefore sets the unit 142c to the proper "tens" numeral. Now the unit 142d controls the setting for the third or units numerals of the number dialed and to that end the magnet 150d has one terminal connected by a wire 230 to the third contact point 163 while its other terminal is connected by a wire 231 to the battery positive wire 195. Upon the completion of the dialing of the second number the second dial circuit will be again closed and the arm 167 will move to this third unit 163 and thereby set the unit 142a in position for acting on the unit 142d so that as the third numeral or unit numeral of the number is dialed a series of impulses or energizations corresponding to that third number will be given the magnet 150d and the arm 177 will step up to engage the proper contact 176. Now, all of these contacts 176 are individually connected by wires 232 to the contacts of groups of contact points 233 and 234, the contacts having like position being connected in multiple to the same contact point 176. Now it is to be observed that the group 233 is opposite the group 227 while the group 234 is opposite the group 229 which is the twenties group.

On the selector is a contact 235 which moves upwardly with the selector and successively traverses the contacts of the group 234 and the contacts of the group 233. A second similar contact 236 likewise carried by the selector successively engages the contacts of groups 229 and 227. From the contact 235 extends a wire 237 which leads to a magnet 238 which may be termed the selecting latching magnet and the operation controlled by which will be hereinafter described. Correspondingly the contact 236 is connected to the magnet 238 by a wire 239. Now the finger 175 is connected to the battery negative wire 206 by a wire 240. The finger 177 is connected by a wire 241 with the contact 188 and from the contact 190 which normally engages the contact 188 a wire 242 leads to the battery positive 195. Now we may suppose that the dialing of the number selected has been effected and the fingers 178 and 177 moved to the proper contacts 174 and 176 respectively. Then the corresponding contact points of the sets traversed by the wipers or contacts 235 and 236 will be energized so that as these wipers come in contact therewith a circuit will be closed. An example of this has been indicated in the wiring diagram by showing the wipers in dotted positions as raised from their normal positions where they are shown in full lines. This ex-

ample corresponds to a number ending in 15. Now as the selector rises no effect will be produced by the engagement of the contacts 235 and 236 until they reach the energized contacts 233 and 227 respectively whereupon current will flow from the battery positive wire 195 through the wire 242, contact 190, contact 188, wire 241, finger 177, contact 176 wherewith that finger engages, wire 232, energized contact 233, contact 235, wire 237, magnet 238, wire 239, contact 236, energized contact 227, wire 226, contact 174, finger 178, and wire 240 back to the battery negative 206.

15 Now when the dialing of the number is completed then magnet 150a will be energized for the third time and the finger 167 will move to the fourth contact 163 which is connected by a wire 243 with the magnet 150e, the other 20 terminal of this magnet being connected by a wire 244 with the battery positive wire 195. Now this magnet 150e by its successive energizations controls the shaft 147 of the unit 142e which is the volume control unit and by 25 suitable mechanism connected to or operated from the shaft 147 of this volume control unit any of the means commonly used to control the volume of the sound produced by the instrument may be operated. It is obvious that 30 the mechanical connection between the shaft 147 of this unit and the volume control of the reproducing instrument itself will vary in accordance with the type of volume control used and the operation of the magnet 150e 35 may be such as to either effect increase in volume or decrease thereof as is best adapted for the particular construction of the reproducer in which this attachment is built. Now it will be observed that the action of the magnet 150e is controlled by the dial and the number of energization for this magnet may be 40 varied by dialing an additional or fourth numeral to close and open the first dial circuit the required number of times thus, after dialing 45 the record number all additional impulses caused by the opening and closing of the first dial circuit will be transmitted to the volume control unit operating magnet 150e so that the volume is completely under control of the 50 operator at the dialing station. Furthermore, it will be noted that where a number of dialing stations are used after the dialing of one record number is accomplished and the volume control unit cut in at one of such stations the finger 167 will have moved to the 55 volume control contact 163 and therefore no other dialing station can operate to effect any change in the record selected since the circuits for this purpose will at that time be cut 60 out. Obviously, the stop element of unit 142a will be so arranged that further operation of the dial circuits after the finger 167 has engaged the fourth contact 163, will not effect any further movement of said finger but the 65 finger, until released in the proper manner,

will remain in contact with said fourth contact 163. The unit 142f is known as the emergency unit and the magnet 150f of this unit has one terminal connected by a wire 245 with the battery positive wire 195 while its other terminal is connected by a wire 246 with a spring contact 247 engaged by the contact 220 when the latter is moved under the influence of the wiper 219. Thus, immediately following the starting of the selector upwardly, circuit will be closed through the magnet 150f as follows; from the positive battery wire 195, through wire 245, magnet 150f, wire 246, contact 247, contact 220, wiper 219, wire 205, and wire 140 back to the battery negative wire 206.

Now it will be remembered that each of the units is provided with a release magnet 151 and that the operation of these magnets is to effect restoration of the fingers of these units to their normal positions. The release magnet 151e is directly controlled from the volume control button of the dial box and to this end the first energized magnet 150e moves the contact 179 into engagement with the contact 178 and any further energizations of this magnet 150e simply keep the contact 179 in engagement with said contact 178. The contact 178 is connected by a wire 247 with the binding post 47. The contact 179 is connected by a wire 248 with the magnet 151e which is in turn connected by a wire 249 with the wire 244 and thus to the battery positive 195. This circuit will be open so long as the circuit closer 38 remains open but upon pushing the volume control button and closing the circuit closer 38 current will flow from the battery positive wire 195 through wire 244, wire 249, magnet 151e, wire 248, contact 179, contact 178, wire 247, binding post 47, wire 65, circuit closer 38, wire 63, wire 61, wire 62, binding post 45, and wire 88 back to the negative side of the battery. Thus when this button is pushed the volume control is released.

The release magnet 151a is connected by a wire 250 with the wire 222 and thus to the battery positive wire 195. The other terminal of this magnet is connected to a wire 251 which extends to the contact 180 in emergency unit 142f. The contact 182 is normally in engagement with the contact 180 and a wire 252 leads from the finger 182 to the binding post 46. The releasing magnet 151b is connected by a wire 253 with the battery positive wire 195 and by a wire 254 with the wire 251. Similarly, the release magnet 151c is connected by a wire 255 with the battery positive wire 195 and by a wire 256 with the wire 251. Now so long as the magnet 150f has not been energized and the finger 182 contacts with finger 180 circuits may be established through the release magnets 151a, 151b and 151c as follows. To these magnets from the battery positive, wire 195 through the respective wires 250, 253 and 255 to the magnets, 125 130

from magnet 151a, through wire 251 and from magnets 151b and 151c through the respective wires 254 and 256 to the wire 151 and thence to contact 180, finger 182, wire 252, binding post 46, wire 64, circuit closer 37, wire 63, wire 61, wire 62, binding post 45, and wire 88 back to the negative side of the battery.

- If, however, the magnet 150f has been energized then the finger 182 will move off 10 the contact 180 and will engage the contact 181. From this contact 181 a wire 257 leads to a magnet 151d and from this magnet a wire 258 leads to the battery positive wire 195. Under these circumstances when the 15 emergency button 37 is pushed current will flow from the battery positive wire 195 through wire 258, magnet 151d, wire 257, contact 181, to finger 252 and thence back to the negative side of the battery as before.
- 20 The release magnet 151f has one terminal connected to the wire 245 and thus to the battery positive wire 195 by a wire 259 while its other terminal is connected by a wire 260 to one side of a multiple point switch 261 having its other side connected to the wire 257 by a wire 262. This switch, as will be presently explained, opens as the selector starts to rise and is closed as the selector resumes its normal position at the end of operations. This switch, due to its function of effecting restoration of all circuits to normal is called for convenience the clearing switch. Similarly, the first side of the clearing switch is connected by a wire 263 to the wire 251.

35 The elevator

Between the upper and lower parts of the frame extend the vertical front and rear guide rails 264 and 265 respectively and on 40 each of these rails runs a small carriage having side plates 266 and guide rollers 267. These guide rails are of channel form with their channels confronting.

- Each of the chains 121, besides engaging 45 the sprockets 120, passes over a series of insulated idler sprockets 268 so as to bring certain parts of these chains into alinement with the rails 264 and 265 on the outside thereof. Each of these chains has one link in the form 50 of a bar 269 on which fits a block 270 held in adjusted position on the bar by a set screw 271. This block has a tongue 272 fitting between extensions of the sides 266 but insulated 55 therefrom as are the screws 273, which hold the parts together. Thus these carriages move with the chains 121 while being insulated therefrom. It may here be noted that the front rail 264 carries negative current and 60 the rear rail 265 carries positive current. Also the front chain 121 carries the current which controls the magnet 123 which throws in the clutch for driving the chains to lift the elevator while the rear chain 121 carries current 65 for the magnet 110 for lowering the elevator.

Pivoted to each of the carriages on a pivot 274 is a hollow tubular arm 275 and each of these arms connects at its upper end to the elevator body pivot 276 mounted each on a respective plate 277 of bakelite or other insulating material. From the rear block 270 a wire 278 leads up through the rear tube 275, across and down through the front tube to a lower contact 279 mounted on an insulating plate 280. On this plate is also a second contact 281 from which (see diagram) a wire 282 leads to the front block 270. Mounted on the plate 280 are guides 283 through which slides a rod 284 carrying a movable contact 285 which oscillates between the contacts 279 and 281 and is arranged to lie in neutral position between said contacts in one position, to engage contact 279 in a second position and contact 281 in a third position. This contact is in electrical conductive engagement through the part 266 with the negative rail 264, this rail being shown as connected (in the diagram) by a wire 286 with a contact point 287 engaged by the contact 288 (Fig. 4B) upon energization of magnet 123. From this contact 287 runs a wire 289 which connects with the brake magnet 290 which is in turn connected to the battery positive wire 195 by a wire 291. This magnet 290 releases a normally active brake 292 operating on a brake drum 293 fixed on a shaft 294 carrying a gear 295 meshing with one of the gears 118 and it is to be observed that this brake magnet operates only on downward movement of the elevator, that is when the downward motion clutch 114 is engaged. Now the shaft 119 is divided into insulated sections by the insulating coupling 296 and on the rear section of this shaft bears a brush 297 which is connected by a wire 298 with the magnet 110 from which a wire 299 runs to the battery positive wire 195. Similarly, a brush 300 bears on the other (front) section of the shaft 119 and is connected by a wire 301 with the magnet 123, the magnet being also connected with the battery positive wire 195. In this manner the chains are connected to the positive side of the battery and form parts of separate circuits.

Now, the rod 284 is shifted to move the contact 285 to its several positions by certain means presently to be described.

This motion changing switch is best seen in detail in Figures 24 to 28 where those parts of the mechanism which move with this switch to effect its changes are shown. From these figures it will be seen that there is mounted on the plate 280 a pair of guides 303 through which slides a bar 304. On this bar are slidably mounted the arms of a yoke 305. Projecting from this bar 304 is a striker lug 306 which, as the carriages 266 almost reach their upper-most position is adapted, under certain conditions, to engage a striker bar

307. The vertical position of this bar is regulated by mechanism presently described but it is deemed desirable here to point out that in its normal position this bar only pushes the bar 304 to neutral position which, as will be presently understood, moves the contact 285 to neutral position so that circuit is broken through the raising magnet 123 but is not established through the lowering magnet 110 and the motion of the chains is thus stopped. However, upon certain steps in the movements of the upper parts or carriage of the device, the bar 307 is pushed downwards so that contact between contacts 285 and 279 is made and circuit through the lowering magnet is thereby established. On the yoke 305 is a dog 308 and mounted on the plate 280 is a bar 309 having spaced notches 310 into which the dog engages at each end of the motion of the yoke so that the yoke is locked at these points. To release the dog at the proper times the bar 304 is provided at its ends with arms 311 carrying fingers 312 having spaced cam ends 313. Between each arm of the yoke 305 and the member 306 is a spring 314 coiled around the bar 304. The action of these parts is thus, assuming the parts to be as in full lines in Figure 25. Upward movement of the lug 306 compresses the upper spring and urges the yoke upwardly. The yoke cannot, however, move until the lower cam finger 313 engages the dog 308 and lifts it out of the lower notch 310 whereupon the yoke flies upward and carries with it the bar 284 which is attached to the yoke. Thereby the contact 285 is moved to the contact 281. Obviously, downward movement of the lug 306, when the parts are in dotted lines position, will restore the parts to full line position in like manner. To effect positioning in neutral position the bar 309 is provided with a pair of pivoted lifting fingers 315 which lie beneath the respective notches 310. These fingers are directed toward each other from their pivot points and their ends are beveled so that the double beveled end of a lever 316, pivoted to the plate 280 intermediate its ends, may lie beneath these ends and effect raising of the fingers and release of the dog in accordance with the movement of the lever 316. Extending from top to bottom of the front of the device is a rod 317 the principal purpose of which, with its companion rod 318 at the back is to guide and support the record selector as will be presently set forth. Near the top of this front rod 317 is fixed a finger 319 which is so positioned that it is engaged by the lever 316 to move it and free the dog 308 just before contact is made by the dog 306 with the push bar 307 so that this bar moves the parts to neutral. In like manner there is a second finger 320 fixed adjacent the bottom of the rod 317 for freeing the dog at the bottom of the path of the front carriage 266. Similarly, to the push bar 307 there is provided at the bottom of the machine a push bar 321 which lies in the path of the lug or dog 306 to move it upwardly. This push rod in its normal or downward position moves the contact 285 just to neutral but to start the carriage in its upward movement there is provided at the lower part of the machine a bellcrank lever 322 so arranged that one arm carries the armature 323 of a magnet 324 which is connected (see diagram) by a wire 325 to the contact 166 of the selector unit 142a, this being the contact which is engaged by the contact arm 169 after the third figure of the number chosen has been dialed. This arm 169 is connected by a wire 326 with the positive battery wire 195. The other side of the magnet 324 is connected by a wire 327 with a fixed contact 328 adjacent the bottom of the apparatus. The contact 328 is adapted to be engaged by a finger 329 fixed to the front carriage and thus, through the connection of this carriage with the front bar 264 connected to the negative side of the battery. Now this finger 329 is so positioned that it engages the four point switch or clearing switch before it engages the contact 328 so that in the downward movement of the carriage at the close of operations the selector unit 142a will have been restored to its normal position prior to the time at which the finger 329 engages the contact 328 by the closing of the four point or clearing switch. However, when the number has been dialed the second dial circuit will be closed at the start of operations through these parts from the battery positive 195 through wire 326, arm 169, contact 166, wire 325, magnet 324, wire 327, contact 328, finger 329, rail 264, and thence back through wire 326 as previously described to the negative side of the battery. Now, at this time the bellcrank 322 will operate to lift the rod 321 and consequently bring the central contact into engagement with the contact 281 to close the upper clutch circuit or circuit through the magnet 123. At the same time it will be observed that the contact point 166 is connected by a wire 330 to the binding post 51 and thus through the green light 30 and wires 68 and 62 to the binding post 45 and the wire 88 to the negative side of the battery. Thus the green light signals that the arm 169 has been positioned on the contact 166 and the parts are in operation.

Fixed upon the carriage 266 is a switch plate 331 which carries at its upper end a roller 332. Pivoted to this plate is the lower end of a lever 333 also provided with a roller 334 which is so positioned as to cooperate with the roller 332. A shaft 335 is carried by the plate 331 and on this shaft is mounted a ratchet wheel 336 so positioned as to be engaged by a pawl 337 pivoted to the upper end of the lever or arm 333. Thus when the

arm 333 is swung in one direction, the ratchet 336 will be rotated while, as the arm 333 swings backward under the influence of the spring 338, the pawl will move over the ratchet more freely. This ratchet 336 revolves freely on the shaft 335 but on this shaft is an escapement wheel 339 which has spring connections with the ratchet 336 so that as the ratchet is rotated by the pawl 337, the spring is wound up. Pivoted to the plate 331 is an anchor pallet 341 one arm of which normally engages one of the teeth of the escapement 339 while the other arm, as usual, lies free from said teeth but in position to engage a tooth upon the first arm being freed from the tooth with which it is engaged. This escapement lies in the path of a lug 342 projecting from the arm 333 so that as this arm moves to rotate the ratchet 336 and reaches a given point, the lug 342 will engage the anchor pallet 341 and moves the same to allow the escapement wheel 339 to revolve one half tooth. Upon the arm 333 resuming its normal position, the anchor pallet 341 swings back and the escapement again moves forward one half tooth, the normally engaged arm of the pallet being engaged by the succeeding tooth of the escapement. This escapement is fixed on the shaft 335 and there is also fixed on this shaft a four-lobed cam 343 so arranged that with each revolution it raises and depresses the arm 344 of a lever mounted on the pivot of the anchor pallet four times. The other arm of this lever is indicated at 345 and will be seen in the form of a spring carrying a contact point 346 which, when the lever is moved to rest on a high point of the cam, will engage a fixed contact point 347 mounted on an arm 348 which is secured to the switch plate 331 but insulated therefrom by the insulation 349. In natural construction, the contact 346 is connected through the metallic part through the negative rail 264 but for illustration in the diagram a wire 350 is shown as running from this part to said negative rail. The contact point 347 is connected by a wire 351, which runs up through the hollow arm 275, to the grip actuating magnet 352 and from the magnet runs a wire 353 which connects the magnets to the metallic part so that they are grounded on the positive rail 265. Thus with each one-eighth revolution of the cam 343 a circuit is closed through the gripper actuating magnet and with the next one-eighth of the revolution the circuit is again opened.

It will be remembered as previously described, that for a portion of the travel of the elevator or gripping device the record selector travels therewith and at a certain time in the operation, the record selector stops and the elevator first moves slightly upward and then downward to take position along side of the upper part of the record selector.

On the elevator is mounted an arm 354 which terminates in an upwardly directed lanceolate cam finger 355 so positioned that as the elevator moves down along side of the upper part of the selector, the point of the cam finger 355 will enter between the rollers 332 and 334 and thus force the roller 334 away from the roller 332 and cause operation of the arm 333 and consequent operation of the ratchet, the escapement, and the cam 343 so that a circuit will be closed by the action of the cam moving the contact point 346 into engagement with the contact point 347, this circuit passing through the gripper magnet to operate the gripper. The magnets 352 are mounted in a housing 356 of inverted U-shape and between the magnets is a guide sleeve 357 wherein slides a rod 358 carrying an armature 359 which is prevented from moving too far away from the magnet by a set screw 360. Fixed to the armature 359 is a yoke 361 to which is hinged the upper edges of a pair of grippers 362 lined with soft rubber as shown at 363 and having on their outer lower sides cam enlargements 364 which slide between the ends of fixed camming pieces 365 so that, upon energization of the magnets 352 the grippers 362 will be drawn upwardly and, by the camming effect of the parts 364 and 365, will likewise be forced inwardly to grip the record which has its edge projecting between said gripping jaws 362. Fixed near the upper part of the machine is a double pointed cam member 356' so positioned that the carriage 266 in its upward movement causes the rollers 332 and 334 to engage this cam member a short distance before the carriage reaches the uppermost part of its movement, the rollers passing off of the upper end of this cam just at the instant the upward movement of the carriage 266 ceases. Obviously, in the upper movement of the carriage this will affect the parts so that the cam 343 is rotated a second one-eighth of a revolution and the lever arm 344 drops into a low part of the cam and contacts between the contact 346 and contact 347 is broken so that the circuit through the gripping magnet is broken. Now in order to delay this action, beyond the center point of the cam 356' both in upward and in downward movement, there is provided on this cam 356' a movable cam finger 357' pivoted in a recess 358' in said cam so that it may swing from the position shown in full lines in Figure 24 to the position shown in dotted lines in that figure. It will now be obvious that the full timing effect, which is necessary to cause the full one-eighth rotation of the cam 343 will be produced in the upward movement of the carriage 266 as the roller 334 passes over the upwardly inclined or dotted position of the finger 357'. As will be presently explained the breaking of the contact by this cam 356' and the resultant release of the gripper jaws

from the records, takes place just at the instant when the carrier grasps the record. In the downward movement of the carriage 266 in replacing the record in its rack, the cam 356 again acts to rotate the cam 343 a third one-eighth of a revolution and closes the circuit at the contact 346 and 347 so that the jaws 362 grip the record just as it is released from the carrier. The record is then carried down and, by means of the selector as will be presently described, is guided into its proper position in the rack from which it was removed. At this time, the finger 355 again passes between the rollers 332 and 334 and cam 343 is rotated through the fourth one-eighth of its revolution so that the arm 344 drops into a lower space on this cam and the circuit through the gripper magnet is broken and the record released to lie in its restored position.

On each of the journal members 276 of the elevator is a pair of rollers 366 which work in the grooves or channel of the respective rails 264 and 265. Fixed on these journal members 276 are arms 367, each of which carries a roller 368 adapted to engage and travel on the curve guide rails 369, best seen in Figure 3A and Figure 5A. By means of this arrangement as the rollers pass into one or the other of the Y branches 370 of the guide rails, the rollers 368, it will be observed that one of the rails 369, the left hand rail in Figure 3A, is positioned toward the front of the machine, while the other rail 369 is positioned toward the rear of the machine and that correspondingly the rollers 368 are offset so that as the carriages 266 reach their uppermost positions the rollers 366 and 368 will be so acted upon by the rails 369 and Y branches that the elevator will be brought into a horizontal position so far as regards the magnet 352 and the gripping jaws as it is in this position that the record is delivered to the carrier. Now since the record, in its upward movement in the grip of the elevator, hangs perpendicularly, the side of the record present uppermost in playing position will depend upon whether the rollers 366 pass into the right branch of each Y or into the left branch thereof, and to effect selection of the branch into which said rollers will pass there is provided at the junction of the Y branches a switch point 371 which is controlled by a mechanism presently to be described.

It may here be explained that the highest point to which the carriages 266 travel is about an inch or so after the grip has been released so that the carriage, which grasps the record just at the time of release by the gripping jaws, is not interfered with in its action since these jaws move laterally, due to the said final upward movement of the carriages, a sufficient distance to free the gripping jaws from the record altogether and thus leave

the record free to be handled by the carrier.

The record selector

The record selector is provided with a pair of end frames 372 which support brackets 373 carrying rollers 374 which roll on the inner edges of the members or rails 317 and 318, the rails being twisted slightly so as to present edge portions inwardly for these rollers to act upon. The portions whereon the rollers act are notched with notches 375 spaced correspondingly to the spaces between the records in the rack. These end frames 372 are connected by a plate 376 and at one end of this end plate are the magnets 238, the action of which was previously described so far as the establishment of the circuit therethrough. Pivoted to the plate 376 is a lever 377 which is connected to a latch rod 378 adapted, when the magnet is energized, to engage in the selected notch 375, it being remembered that this magnet is only energized when the contact fingers 235 and 236 contact with energized contact points as previously described. Also, there is a second similar rod 379 which engages in the notches 375 of the rear rail 318. Mounted on the plate 376 is a pivot pin or shaft 380 carrying a disk or crank plate 381 to which the rods 378 and 379 are connected by linkage 382 in such manner that as one of these rods move in one direction the other will move in the opposite direction. Therefore when the magnet 238 is energized and the rod 378 is moved to engage in the proper front notch 375 the rod 379 will be similarly moved to engage in a rear notch 375. At the opposite or rear side of the plate 376 is a second pair of magnets 383 which are electrically connected with the rail 318 so that they are thus connected to the negative side of the battery. Now these magnets are also connected by a wire 384 with a movable wiper or contact 385 which is supported on a pivoted arm 386 carrying a pin 387 operating on a flange 388 which is driven by the fixed tooth ratchet wheel 389, the cam being so arranged that rotation of the wheel 389 through three teeth will move the cam to bring the wiper 385 in position to contact with a pin 385' fixed on the carriage 266 which travels on the positive rail, and thus establish circuit through the magnets 383. Now this ratchet 389 is operated in the following manner, the elevator is provided at the lower ends of its arms with a pair of supporting blocks or plates 390 over which the ends of the rods 378 and 379, opposite those ends which engage in the notches 375, engage when the magnet 238 is de-energized and the magnet 383 is energized, this magnet being provided with a lever armature 391 which is connected to the rod 378. Now normally, in the upward movement of the record selector, the magnet 238 is not energized and the record selector moves upward because the ends of the rods 378 and 379

379 rest on the blocks or plates 390 which are carried upwardly as the carriages 266 move upwardly under the influence of the chain. However on arriving at the proper position 5 the magnet 238 is energized and the rods 378 and 379 are urged outwardly by the action of this magnet. This energization of the magnet takes place at a point slightly above the point at which the rods will engage in their 10 proper notches so that the record selector actually drops back a short distance away from the elevator. It will be noted that this dropping backward of the record selector breaks the contact of the contacts 235 and 15 236 with the energized contact points 233 and 227. Meantime, the elevator moves upward until, as previously described, the motion of the chains is reversed whereupon the elevator moves downwardly and in so doing a pawl 20 392 on the rear carriage 266 engages the ratchet 389 and turns the same one tooth or one-sixth of a revolution. This movement of the elevator is the one in which the elevator grips the record and on reaching the bottom 25 of this movement, the elevator reverses as previously described and the pawl 392 passes up by the ratchet 389, riding freely thereover. The next downward movement of the elevator takes place, so far as affects the ratchet 389, when the record is replaced in its rack. 30 In this movement, the pawl 392 engages the ratchet 389 and turns it a second tooth. The elevator now rises and reverses and again descends. On this downward movement, the 35 elevator moves downwardly until the plates 390 are spaced slightly below the rods 378 and 379. At this point in the motion, the pawl 392 engages and turns the ratchet 389 where- as to bring the wiper or contact 385 into en- 40 gagement with the contact 385' by the action of the cam 388. The effect of this is to es- tablish a circuit through the magnets 383 which in turn causes withdrawal of the rods 378 and 379 from the notches 375 and the pro- 45 jection of these rods over the plates 390, so that the record selector drops slightly until these rods rest on the plates, the elevator thus carrying the record selector downwardly to its normal or rest position. It is to be noted 50 that the dropping of the selector with rela- tion to the elevator breaks the contact be- tween the contact member 385 and the lug 385' so that the magnet 383 is de-energized and the parts left free for the action of the 55 magnet 238.

The apparatus for guiding the elevator in its record gripping movement and the elevator and records in the movement for replacing the record in the rack will now be de- 60 scribed. The end members 372 are extended upwardly and between the upward extensions is a cross-plate 394 made of suitable insulating material. This cross-plate is supported in the upwardly extending ends by trun- 65 nions 395, fixed on each of these trunnions.

is a cam member 396 the shape of which is clearly shown in Figure 29, the cam members being right and left hand respectively. It will also be noted, from Figure 29, that the plate 394 in its normal position is inclined 70 in such a manner as to direct the elevator toward the right hand record rack, stops 397 being provided for limiting its movement in this direction. Projecting from the rear trunnions 395 is a rock arm 398 and extending downwardly from this rock arm is a jointed trip link 399, the lower end of which passes through a guide 400 fixed on the rear plate 390 and this broad end is provided with a head 401 adapted, upon energization of 80 the magnet 208, to be engaged by a hook end on an armature 402 pivoted to and controlled by said magnet 208. It will be remembered that it has been set forth previously that the magnet 208 is energized whenever the first 85 numeral of the dial is such that the record corresponding to the number being dialed is in the left hand rack. With respect to the latch members 397 it will be observed that one of these members is pivoted to the plate 90 394, being urged against the other member by a spring 403 and that the fixed member 397' is of arcuate form and has a notch 404 in its rear end. A trip pawl 405 is mounted on a rod 406 in such position that, as the pawl 95 moves in one direction, the spring pressed member 397 is forced out of the notch, if en- gaged therein, and the plate 394 restored to its normal position. On the lower end of this rod 406 is a finger 407 which, when the device 100 resumes its normal position with the elevator and record selector at the bottom, engages a fixed cam member 408 so that the finger 407 turns the rod 406 and thereby effects its en- gagement of the spring pressed latch 397. 105 Fixed on the upper edge of the plate 394 is a pair of record guide fingers 407' directed respectively to the right and left sides of the plate and pivoted to the guide fingers are 110 guide extensions 408' normally held inwardly 115 toward the plate 394 by springs 409. Each of these guide fingers 408' is provided with a laterally extending portion 410 which rests against a four sided cam 411 fixed on a shaft 412 supported on the plate 394 and carrying 115 a four toothed ratchet 413. Spring pawls 414 are carried by the elevator insulating plate 277 and are positioned to engage the ratchet 413 selectively in accordance with the 120 side of the selector to which the elevator is guided, the ratchet being engaged by these pawls on the upward movement of the eleva- 125 tor. Normally, the extensions or fingers 410 of the respective guides 408' rest on a low stop on the cam 411 so that when the gripper 130 grips a record and the elevator attends, the turning of the cam 413 will bring the finger 410 on the high spot of the cam 411 and will thus project the extension guide 408' into proper position to guide the record in its re-

placement in the rack. After the elevator has released the record in replacing the same and again rises the pawl 414 will turn the ratchet 413 to one more quarter and consequently the finger 412 will be restored to a low spot on the cam 411.

The action of the reversing switch shown in Figure 25 has previously been described without reference to those parts which engage the lug 306 to cause the reversal. Such parts will now be considered. Projecting from the front plate 372 is an arm 415 which supports a depending plate 416 having an opening 417 therein which is crossed by the shaft 418 suitably journaled on the plate 416. Fixed on this shaft 418 is a four toothed ratchet 419 beside which is a cam 420 having two high and two low spots. Mounted on the plate 416 is a latch member 421 having a projecting end 422 and these parts are so positioned that when the cam 420 moves to bring a finger 423 attached to said latch member on one of the high spots it moves the end 422 into position to be engaged by the lug 306 in the upward movement of the reversing switch. However, when the finger 423 rests on the low spot on the cam the end 422 is retracted so that the lug 306 may pass freely without engagement and consequently without reversal of the operation of the switch. Also, there depends from the plate 416 an arm 424 which has an adjustable stop 425 for engagement with said lug 306 on its downward movement. Mounted on the reversing switch is a hook pawl 426 which engages the ratchet 419 to rotate the same on the downward movement of the elevator and switch. It will be remembered that after the selector and elevator have moved to the proper position for the selector, the elevator reverses and moves downwardly. This is because, as the selector dis-connects from the elevator, the elevator travels on upwardly and the lug 306 engages the end 422 which is normally projected in the path of said lug. This of course reverses the action of the switch and the elevator moves downwardly. Upon this downward movement, ratchet 419 and pawl 420 are actuated to free the end 422 from the path of the lug 306 so that after this lug strikes the stop 425 and reverses the motion of the elevator to upward motion it will now pass free without the lug 306 contacting with the end 422 so that the upward motion continues and the record may be carried upwardly. In the restoration of the record, the elevator of course moves downwardly and in its first action passes down until the lug 306 contacts with the stop 425. In this downward passage the ratchet 419 and cam 420 are again actuated and the end 422 moves outwardly so that when the switch reverses by contact with the stop 425 it will move upwardly until the lug 306 strikes the end 422 whereupon it will again reverse and resume its downward

movement so that the parts now move to normal or rest position.

In order to prevent improper swinging of the record and gripper after the record has been withdrawn from the rack and is being elevated or while the record is being lowered, there is provided on top of the front arm 275 a small arcuate member 426 having a shallow notch 427 in the center of the arc. On the swinging portion of the gripper is carried a spring pressed dog 428 which travels over the member 426 and which in so travelling drops into the notch 427 to hold the gripper and record perpendicular in its travel up and down. The notch 427 is so shaped and is of such depth that, while it will prevent such improper swinging, it will allow, at the proper time, the dog 428 to ride out of the notch 427 and the gripper and record to assume the proper position at the end of the travel of the elevator.

The record carrier or transfer device.

Fixed to the frame are the carrier supporting rails 429 and 430, the front rail being shown at 429 and the rear rail at 430. This front rail is provided with rack teeth facing upwardly so that the front rail 429 forms a shrouded rack. The turn table of the reproducing instrument is shown at 431 and it will be observed that the rails 429 and 430 extend to the right to a line substantially central of the turn table so these rails may terminate at any convenient or necessary position with relation to such turn table. What may be termed the primary traversing frame, best seen in Figure 2, consists in the main of a pair of side bars 432 which are held in spaced relation by brace bars 433 each having one end connected to a respective frame bar 432 and its other end connected to a central insulating plate or platform 434. Thus the bars 432 are insulated from each other. At the rear, this primary traversing frame is supported on the rear rail 430 by rollers or wheels 435 and the front right carriage of the frame is supported by a gear 436. At the front left side of the frame there is a bracket 437 and in frame member 485 and this bracket 437 is journaled a shaft 438 which has its ends insulated from each other and an insulating coupling being employed for this purpose. Moreover, the bracket 437 is provided with an insulating bushing 440 through which the rear end of the shaft 438 passes and a gear 441 is mounted on this rear end. On the front end is mounted a gear 442 which engages the rack of the front bar 429 and constituted, as will be presently observed, the driving gear by means of which the primary traversing frame is moved to the right or to the left as the case may be. It will now be seen that by this construction the gear 441 is insulated from the gear 442 and consequently from the rack rail 430 is a brush, this being 130

necessary because this rack rail acts as a conductor, the front rail being negative and the back rail being positive. That is to say, the front rail is connected to the negative side of the battery and the rear rail to the positive side of said battery. Journaled in the upper part of the main frame and extending transversely from the left hand side thereof toward the turn table 431 is a drum gear 439' on the left hand end of which is a bevel gear 440' with which meshes a bevel gear 441' fixed on the upper end of the shaft 103. Thus, when the motor drives the shaft 103 the drum gear 439' will be driven. Journaled in suitable bearings on the insulating plate 434 is a shaft 442' on which is fixed a gear 443 which meshes with and slides along the drum gear 439. This shaft also carries a bevel gear 443' which meshes with a bevel gear 444 carried on a shaft 445 suitably supported from the insulating plate or platform 434. On this shaft 445 is fixed a spur gear 446. Mounted on a pivot 446' supported from the plate 434 is a T-shaped lever 447 carrying at the end of one arm a shaft 448 whereon is fixed a gear 449 while on the other arm is mounted a gear 450 which is constantly in mesh with the gear 449. Means, hereinafter to be described, are provided for rocking this lever 447 so as to bring either the gear 449 or the gear 450 into mesh with the gear 446. Also on this shaft 448 is a gear 451 which meshes with the gear 441, the shaft being supported in such manner as to allow a slight angular play thereof and the change of angular position of this shaft not being sufficient to interfere with the proper meshing with the gears. It will now be plain that the gear 446 is driven so long as the motor is running and that if the lever 447 be tilted to bring the gear 449 into mesh with gear 446 the gear 441, and consequently the gear 442 will rotate in one direction while if the lever 447 be tilted to bring the idler gear 450 into mesh with the gear 446 then the gear 442 will rotate in the opposite direction. The arrangement is such that when the idler gear 450 is in mesh the parts move to the right and when the gear 449 is in mesh the parts move to the left.

50 Mounted on the plate 434 is a base plate 452, see Figure 35, whereon is pivoted one end of an arm 453 from which projects upwardly a vertical shaft 454 whereon is journaled a sleeve 455. This worm gear 456 is adapted to be swung, by the motion of the arm 453, into and out of mesh with a worm 457 fixed on the shaft 442'. Fixed to the upper end of the sleeve 455 is a cup-shaped cam 458, the sides of which are cut away to provide a pair of oppositely disposed high points 459 each of which is flanked at each side by a middle or neutral point 460, the floor of the cup or base providing low points 461. On the plate 434 is mounted a pair of supports 462 carrying at their upper ends a shaft 463 whereon is

mounted a pair of arms 464 having their free ends traversed by a shaft, one end of which is shown at 465 and is engaged by the cam 458 to raise and lower said arm. Between the arms 464 on said shaft 465 is mounted a hanger 466 having its lower end connected with the lever 447. Referring now to Figure 32, it will be seen that the low, intermediate and high points of the cam are indicated by dotted lines and it will accordingly be seen that when the cam is on the intermediate point neither of the gears 449 or 450 are engaged. When the cam is so positioned that the shaft 465 is on the low point, then the gear 449 will be engaged and when the cam is so positioned that the cam 465 is at the high point, the gear 450 will be engaged. Thus, the position of the cam regulates the direction of travel of the primary carrier plate.

55 Mounted on the rear carriage (see Figure 5B) is a lug 463'. Adjacent the upper end of the rear rail 265 is a bracket 464' whereon is slidably mounted a vertical bar 465' connected by a link 466' with a rock arm 467 mounted on a shaft 468 which extends along the inner side of the upper rear main frame member as can be seen in Figure 1A. On the left hand end of this shaft is fixed a rock arm 469 and pivoted on this end is an arm 470 carrying a tilting latch 471 which is normally held, as shown in Figures 38 and 39, in position for engagement by the end of the rock arm 469. Suitable spring means being used to hold it in this position yieldably. Pivotally connected through the arm 470 is one end of a reach rod or link 472, the other end of which is connected to a rock arm 473 mounted on a shaft 474 supported in suitable bearing adjacent the cup cam arrangement just described. On this shaft 474 is also mounted a rock arm 475 having a laterally projecting cam portion 476 which engages the end of an arm 477 projecting laterally from the swinging arm 453, the arrangement being such that when the rock arm 475 is rocked upwardly, the cam assumes the position shown in Figure 37 and pushes the arm 477 to such position that the worm wheel is brought into engagement with the worm gear. A spring 478 is used to normally hold the rock arm 475 downwardly. Pivoted to extend beneath the arm 477 is a latch member 479 which has its free end urged upwardly by a suitable spring and this latch member is provided with a notch 480 for engagement with the arm 477 when the latter is rocked by the cam 476. The end of the latch member 479 is provided with a cam surface 481 which engages beneath a finger 482 projecting from the rock arm 475 so that when thus engaged the latch member 479 is forced downwardly, as shown in Figure 36, and consequently the arm 477 is freed and the worm gear allowed to move out of mesh with the worm. Obviously, when the rock arm 475 rocked upward-

ly to push the arm 477 laterally, the finger 482 rises and allows the free end of the latch 479 to rise and lock the arm 477. It is to be noted that the shaft 474 is supported on a bracket 482 carried, as shown in Figure 4A, on the main frame so that the plate 452 and all parts attached thereto move toward and from the rock arm 475 as the apparatus operates. Thus when the arm 477 is latched in the manner above described, the cam 458 will start working and the driving gear 443 will slide along the drum gear 439, being rotated thereby and thus driving the carrier frame and the cam. The shaft supporting the hanger 466 has its opposite end 483 extended somewhat longer than the end 465 and fixed to the main frame is a cam member 484 so positioned that the end 483 is permitted to ride thereon when the end 465 is lifted to the high spot of the cam.

Resting on the rollers 435 and the gears 436 and 442 are the side frame members 485 which are held in proper spaced relation by brace members 486 having their ends suitably insulated from the members 485 so that these members are electrically disconnected. Now it will be noted that the front member 485 forms a shrouded rack and that by reason of this the secondary carrier frame will travel twice as fast and twice as far as the primary carrier frame. Now let us consider what happens to the carrier frames in their movement across the machine. When the number is dialed and the dialing is completed, the carriages with the selector and elevator will rise and operate in the manner previously described, the elevator finally rising toward the top of the machine. At this time, as the elevator reaches the top, the shaft 468 will be rocked and as just described the worm gear will be meshed with by the worm wheel so that the cup cam 458 will start rotating. When this cam has rotated sufficiently to cause the shaft end 465 to ride up on the high part of the cam then through the gearing before described, the gear 442 will rotate to drive the carrier frame to the right. Now it is to be observed that the first high spot 459 of the cam is considerably longer than the second high spot. In fact, the first high spot is of such length that before the shaft end 465 drops off of this high spot, the end 483 passes onto the fixed cam 484 and, in the motion to the right of the carrier frame fastened across that fixed cam and drops off at the end thereof onto the neutral of the cam 458, calling this the first neutral. The reason for the provision of the cam 484 is to make certain that the gears 449 and 450 will be moved into neutral position at exactly the right time so that the record can be centered over the turn table. At this time, as will be hereinafter explained, the record is dropped on the turn table and shortly after the dropping the end 465 drops off of the neutral onto

the low spot or first low 461 of the cam 458.

Now this first low is considerably shorter than the second low spot so that the carriers are not retracted at this time to their original position but the carrier frame which supports the record, the secondary carrier frame, will only move about one-half way back whereupon the cam will have turned to raise the end 465 onto the second neutral and the parts will come to rest in that position. Under normal conditions at this time the motor circuit will be broken and of course there will be no movement of the cam until the motor again starts. The record having been played, under normal conditions, the motor circuit again starts and the cam begins its further revolution. Accordingly the end 465 is engaged by the second high spot and it is to be noted that this high spot is shorter than the first high spot so that it raises the end 465 just to such position as to permit the end 483 to be engaged by the fixed cam and the carriers will move to the right until the secondary carrier will be in exact position to grasp the records from the turn table. After the record has been grasped and lifted from the turn table, the cam will then have revolved until the end 465 has dropped off the third neutral onto the second low which is of sufficient length to keep the gearing shown in Figure 32 in mesh until the parts are returned fully to their normal or rest position. The action of the parts shown in Figures 38 and 39 will now be particularly explained. Extending from the latch 471 is a trip arm 487 preferably of insulating material and positioned to be engaged by a trip 488 upon movement of the trip 487 to the position shown in Figure 39 and movement of the secondary carrier frame to the right of the machine. It will be remembered that as long as the elevator carriages are up the rock arm 469 will be in the position shown in Figure 39 and consequently the arm 477 will have been moved to lapping position and the worm wheel and worm gear in mesh. It is necessary, that the lever 475 or rock arm be restored to its original position before the carriers return to their positions as otherwise the operation would start at uncertain times because of the fact that the cam would not always be disconnected from the driving worm at the proper instant. Accordingly, just as soon as the carriers have made a certain definite movement toward the right, the member 488 engages the member 487 and throws it downwardly to free the latch 471 from the rock arm 469 so that the parts assume the position shown in dotted lines in Figure 38, that is to say with the rock arm 469 in the position of Figure 39 and the other parts in their normal positions.

The action just described takes place in every instant except when it is desired to repeat the playing of a record already posi-

tioned on the turntable, in other words to play the same music twice without restoring the record to the rack.

The repeater

5   Mounted on the main frame at the left side near the front thereof is a pair of magnets 488' having an armature 489 mounted on a rod 490 which projects rearwardly from between these magnets and carries a cam member 491 which normally lies out of the path of the shaft end 483 but which, when the magnet 488' is energized, is moved to such position as to raise that end 483 to neutral position for the gears 449 and 450 just prior to the time when the carriers would have been restored to their normal or idle position. Consequently, the carrier stops short of this normal or idle position and the worm gear 20 is not unmeshed from the worm since the latch 479 does not come in engagement with the unlatching finger 484 until the carriers are fully in their normal position. Consequently, the cam continues to revolve and the 25 carriers go through exactly the same operation as previously described.

Referring now to the diagram, it will be seen that the magnet 488' is connected by a wire 492 with the long contact 165 of selector unit 142a. The other side of this magnet is connected by a wire 493 with the binding post 41 and set through the wire 67 with the repeat button 40. Consequently, if at any time, after the contact finger 168 has moved 30 onto the long contact 165, the repeat button be pushed, the magnet 488' will be energized and the repeating cam 491 positioned for repeating action. Fixed on the rod 490 is an arm having a flat end, see Figures 41 and 42, 35 as indicated at 494. Fixed on the main frame is an arm 495 having a notch at one side wherein the bevelled tooth 496 on arm 494 engages when the magnet 488 is energized so as to hold the cam in repeating position. At 40 497 is a magnet having an armature 498 pivoted to the main frame member on which the notch 495 is mounted. This armature carries a cam arm 499 which, upon energization of the magnet 497, operates against the bevelled face of the tooth 496 and rocks the arm 494 downwardly to free the tooth from the notch in the latch 495 and permit the repeating cam to take its normal position. The magnet 497 is connected by a wire, see diagram, 500 with the positive side of the battery through wire 195. This magnet is also connected by a wire 501 with a contact 502 adapted to be engaged by a contact 503 carried by but insulated from the rod 490 and 55 this movable contact 503 is connected by a wire 504 through the wire 257 to point 181 of the emergency unit 142f. Thus, if after dialing, the magnet 488 be energized, contact 60 will be established between the contacts 502 and 503 so that when either the emergency

button is pushed or the clearing switch operates, the magnet 497 will be energized and the repeating cam released for restoration to its normal position. Mounted on the member 486 are side bars 505 which support rock shafts 506. On the front shaft is an upwardly extending rock arm 507 which is connected by a link 508 with the lower arm of a double arm rocker 509 supported on a shaft 510, the upper arm of this double arm rocker being connected by a link 511 with a rock arm 512 on the rear shaft 506. This construction can be well seen in Figure 43 of sheet 17. On these shafts are also mounted rock arms 513 which are connected by links 514 with a record lift frame 515 having at each side a rock shaft 516 whereon are positioned record gripping fingers 517 having tips directed toward each other. Extending across the frame 515 is a rock shaft 518 carrying an armature 519 adapted to be acted on by the record finger magnet 520 to rock said shaft and thereby actuate a pair of rock arms 521 which engage with rock arms 522 on the respective shafts 516, the arrangement of the parts being such that the fingers 517 are moved to record engaging position upon energization of said magnet and freed from the record engaging position when the magnet is to be energized. The spring 523 on the shaft 510 normally holds the frame 515 and the record carried thereby in raised position, the strength of the spring being sufficient to overcome the weight of the frame, the magnet and the record.

On the rear elevator carriage, see Figure 5B, is a roller 524 and in the path of this roller adjacent the upper part of this machine is a vertical shaft 525 having a rocking cam member 526 against which the roller operates to rock the shaft 525. As will be seen from Figure 44 this member 526 has a companion member 527 which acts as a support and guide for the roller so that tendency to twist the rear carriage is eliminated. This shaft 525 has fixed on its upper end a rock arm 528 linked to a pivoted cam 528', which, when the shaft 525 is rocked by the action of the roller just described, presses on a link 529 which is connected to the upper double rocker 509 and consequently rocks the shaft 510. Thus when the elevator is near the upper end of its movement, rocking of the frame 515 down is caused so that the fingers 517 are in position to grip the record carried by the elevator at the proper time. Keeping in mind that the front elevator carriage has connection with the negative side of the battery, we may now trace the manner in which current is established through the magnet 520 so as to cause the fingers 517 to grip the record. As the front elevator carriage moves upwardly a lug 356 thereon comes in contact with a spring contact finger 528a mounted on but insulated from a bracket 529a. Contact finger 528a is 120 125 130

connected by a wire 530 with a stationary contact 531, fixed on but insulated from the bracket 531'. Mounted on an insulating base 532 supported on one of the cross members 486 is a fixed contact 533 which is connected by a wire 534 with a contact 535 moved into and out of engagement with a contact 536 by means of a cam device 537 best seen in Figure 2 and the details of which it is not deemed necessary to describe since the construction is practically identical with the ratchet operated cam and switch points of Figure 24. The contact 536 is connected with the negative side of the battery through the metallic parts of the switch as in the previous case. Pivoted on the plate 533 is a spring pressed finger 539 having a beveled end which engages the contact 531, the spring of this finger urging it into such engagement laterally. On this finger is also mounted a spring contact 540. From the finger 539 a wire 541 leads to the magnet 520 which is connected to the positive rail as by the connection 541 shown in the diagram. Normally, with the parts in the position of rest, the contact 535 engages the contact 536. Now it will be remembered that the plate or base 533 is fixed on the moving part of the carriage and consequently when the device is operated, this plate and the contacts supported thereby will move away from the contact 531. Considering now what happens when the elevator rises. Contact is made from the finger 528 through the fixed contact 531 and movable contact 539 to the magnet 520 so that at this time the magnet operates and the gripping fingers 517 grip the record. This takes place just as the elevator gripper lets go. As the roller passes off the upper end of the member 526 the cam piece 528 will rock back and the record will be lifted. Now at this time, motion of the carriage to the right will be begun. Connected to the lower arm 509 is a push rod 542 guided by a roller 543 to push the rock arm 509 and rock the frame 515 downwardly. At the front of the machine toward the right side thereof there is a pivoted finger 544 positioned to engage the push rod 542 upon the record carrying frame being centered over the turn table 481 so that at this time in the movement the record carrying frame is again depressed. At the same time there is provided on the side of the machine an insulated finger 545 arranged to contact with and operate the switch 537. Now the first time the frame 515 moves over the turn table, this switch 537 will be operated to break the circuit through the magnets 520 and the record will be released on the turn table so that the frame 515 may rise and move back to the intermediate position it assumes while the record is being played. Now when it comes back to remove the record from the turn table, the frame will be depressed as before but on this movement, the finger 545 will turn the switch 537 to make contact and again energize the magnets 520 so that they grip the record which is then carried back ready for grasping by the elevator. Of course at this time the elevator will move so that its gripping jaws travel a slight distance horizontally, while the carriage travels vertically downward. When the gripping jaws of the elevator are in proper position with relation to the edge of the record, that is overlapping the same, the contact with the spring finger 528 will be broken so that the magnet 520 will be de-energized and the fingers 517 will move to release the record to the elevator grip jaws. Following this, the shaft 525 will be rocked by the downward descent of the roller past the member 526 and the clearing of this member by the roller at the lower end so that the record carrying frame 515 will be raised. The device which effects closing of the down motion circuit for the elevator upon the carrier resuming its position of rest after it has taken the records off of the turn table and presented it to the elevator will now be considered. In this connection, reference will be had to Figure 3A and to Figure 52, the latter being on (Sheet 16). On the front member 485 adjacent the left hand end thereof is a forwardly projecting pin 545'. The member 307 projects upwardly above the top horizontal frame member and in this upwardly projecting end the guide slot 546 is provided. On the member 307 and below the lower end of this guide slot is pivoted a swinging latch member 547 having a tooth 548 which projects to the lug. The member 547 is normally urged to vertical position by a suitable spring, not shown, so that the tooth 548 has its greatest projection toward the left when the member 547 is vertical. Pivoted to the bracket 549 carried by the frame is an arm or lever 550. This arm or lever has its right hand end in the form of a cam finger 551, while its left hand end projects downwardly as at 552 to lie in the path of the pin 545' as the carrier member 485 reaches its position of rest. Beneath the pivot of the member 550 is a second downwardly projecting portion 553 which is engaged by the pin 545' as the member 485 moves to the right. This finger 553 is of cam-shape so that engagement of the pin 545' therewith, while effecting upward tilting of the finger 551 yet permits the pin to pass from beneath the finger 553 and the part 485 to move on toward the right. Normally, the parts are in the position shown in Figure 3A, that is to say, the pin 545' is engaged with the downwardly projecting portion 552 and the finger 551 depressed and it will be noted that this finger is so positioned that it slips past the tooth 548 as it reaches its lowermost position so that the member 307 may be raised by the spring 554. When the finger 551 is tilted upward, it engages the tooth 548 and rocks the mem-

ber 547 to permit the finger 551 to pass above the tooth 548 so that when the carrier member 485 moves to its position of rest the pin 545' will pass freely beneath the finger 552 since the latter is tilted to the right and upwardly and will engage the finger or end 552 thus forcing the finger 551 downwardly and depressing the member 307 which thereupon engages the lug 306 of the reversing switch 10 and closes the circuit which controls the downward movement clutch. It is to be noted that this same closing of the circuit takes place in the same manner when the carrier member 485 moves to the reversing position 15 for the record but it does not take place since the pin 545' stops in the position it assumed in operating the repeat, since at this time the pin does not come far enough to the left to engage and operate the part 552.

20 It will be remembered that the depression of the frame 515 in placing a record on or removing it from the turn table is effected by the engagement of the push rod 542 with the finger 544. When it is desired to remove 25 a record manually for the substitution of another record or the like, it is not desirable that these frames 515 be depressed at this time. In order to effect such removal it is at times desirable that the carrier and elevator go through the movement of replacing a record in the rack without actually picking the record up off of the turn table and to do this the apparatus mechanism shown in Figures 53 and 54 is employed. The finger 544 is pivoted on a bracket 555 mounted on the frame and a spring 556 urges the finger from the position shown in Figure 53 to the position shown in Figure 54 where, it will be observed that the end of the push 30 rod 542 in moving to the right will clear the end of the finger 544. On this bracket is also mounted a shaft 557 whereon is a bell crank lever 558 carrying a dog 559 which operates against the side of the member 544 to push 35 the same or hold the same against the action of the spring 556. A stop 560 is provided for the other arm of the lever 558 so as to prevent too great movement thereof in one direction and the spring 556 is so arranged as 40 to also effect a snap action on the bell crank lever 558 so as to swing it from the position shown in Figure 53 to the position shown in Figure 54 without permitting it to rest in an intermediate position. On the upper end 45 of the shaft 557 is an operating lever 561 (see Figure 1A) so positioned as to be readily reached by the fingers of the operator. Now when the operating lever is moved from the position shown in dotted lines in Figure 53 to the position shown in dotted lines in Figure 54, the bell crank 558 will move in accordance therewith as shown and the finger 544 will drop to such position as to permit free passage at the end of the push 50 rod 542. Accordingly, after the record has

been played, the lever 561 is moved to bring the parts to the position shown in Figure 54. Then upon the movement of the carrier to the right to take the record off of the turn table, no depression of the frame 515 will be made and consequently the record will not be picked up. The carrier will then return to its normal position and the elevator will go through the motions of returning the record and assuming its normal position without actually doing so, the record being left in position on the turn table. It can then be removed from the turn table and if it is desired to have another record take its place in the empty compartment of the rack, then this record is placed on the turn table and the same member as before is dialed whereupon the elevator and carrier go through the motions of putting the new record on the table. The lever 561 having been moved to clear position as shown in Figure 54 and the carrier will come to rest in its intermediate or record playing position. Now as the carrier moves to the left it automatically restores the parts to the position shown in Figure 53 whenever they are thrown into the position shown in Figure 54. To this end there is provided on the carrier frame a small spring pressed pawl 562 which swings freely toward the left but whose motion toward the right is limited by a stop pin 563. Now, as will be seen by reference to Figure 54, when the parts of the carrier move to the right, this pawl passes over the end of the bell crank lever 558 and drops to the right of it so that when the carriers return to the left, the pawl 562 engages the pin 563 and pushes on the bell crank 558, which, by reason of the spring 556 drops to the position shown in Figure 53 and the parts are restored ready for the next movement of the carrier to the right so that it will again pick up the record from the turn table.

The record reversing mechanism

It will be remembered that a switch point 371 controls the passage of the upper roller on the elevator into one branch or the other of the Y track. Now this switch point 371 is fixed on a shaft 563, there being of course one switch point and one shaft 563 for each of the Y rails or tracks as clearly shown in Figure 56. These shafts project through the rails and on the outer ends of these shafts are fixed rock arms 564 which are connected by links 565 to rock arms 566 fixed on a rock shaft 567 suitably supported adjacent the upper part of the machine at the left end thereof, a shelf being provided for this purpose. On this shaft 567 is a spring 568 to hold it in its normal position which is thus shown in Figure 56. Also, this shaft carries a rock arm 569 whereon is provided an armature 570 and the magnet 202, previously described, is fixed near this shaft so the

the armature 570 is the armature of that magnet. It will be observed that normally the magnet 202 is not energized and does not attract the armature 570 so that the latter is spaced therefrom by the action of the spring 568. Now adjacent this shaft 567 is a second electro-magnet 571 which has an armature 572 attached to a lever 573 which is carried on a rock shaft 574 and this lever 10 also carries a contact 575 adapted to engage, upon energization of the magnet 202 with a switch contact 576 adjacent said contact 575. On the shaft 567 is also fixed an arcuate member 577 having a notch 578 therein and on 15 the shaft 574 is a finger 579 which, when the magnet 202 is energized the magnet 571 not being energized, drops into the notch 578 and locks the shaft 567 in such position that the switch point 371 is moved to the right as 20 shown in dotted lines in Figure 55. Thus normally the elevator travels up the right hand side of the Y while upon energization of the magnet 202 this elevator travels up the left hand side of the Y. The contact 25 575 is insulated from the lever 573 that is connected with the magnet 571 by the wire 580 and the other terminal of the magnet 571 is connected by a wire 581 to the battery positive wire 195. The contact 576 is connected by a wire 582 with the side 260 of the 30 clearing switch so that every time the clearing switch operates at the end of the entire cycle of operations the magnet 571 will be energized, providing magnet 202 has been 35 energized causing the position of shaft 567 and associated parts to be changed; said change in position being locked by finger 579 dropping in notch 578, the change also causing or permitting the armature 572 to drop 40 away from magnet 571 thus effecting closing of contact between contacts 575 and 576 and the parts restored to their normal position. It will now be remembered that it 45 has been previously described that the arm 172 in its passage over the contact point 170 of the selector unit 142b operates on reaching the second contact point to establish a circuit through the magnet 202; on reaching the third contact point to establish a circuit 50 through magnet 208 and upon reaching the fourth contact point you establish a circuit both through the magnet 202 and the magnet 208, by energization of magnet 211 through wire 210, this energization causing contact 55 to be made between movable contact 212 and the fixed contacts 213 and 214 which lead to magnets 208 and 202 respectively. Thus for even number dialings of the first numeral of 60 the numeral dial, the switch point 371 will occupy the position shown in dotted lines in Figure 55, while, if the first numeral dial be an odd number, the switch point will remain in its normal position as shown in full 65 lines in said figure.

Referring now to Figure 3A, 57 and 58, it will be seen that there is fixed on the rail 317 a bracket or frame 583 through which slides a pair of rods 584, carrying on their right hand end a magnet armature bar 585 and between the sides of the frame 583 is a pair of magnets 586 arranged, when energized, to attract the bar 585. This bar 585 carries a rod or plunger 587 and the bar is held normally away from the magnets by a spring 588. At right angles to the magnet 586 is a pair of magnets 589 which are arranged to attract an armature 590 carried on a rack arm 591 which is supported on the rocking shaft 592. This rocking shaft 592 carries a dog 593 which is so positioned and arranged that upon energization of the magnets 586 and consequent movement of the rod 587 to the left the rods will be engaged by the dog 593 and held in the position toward the left until the magnets 589 are energized whereupon the armature 590 will be attracted and the dog 593 will be depressed to allow movement of the bar 585 and rack 586 to the right. Fixed on the left hand ends of the rods 584 and movable therewith is a plate 594 which carries a bracket 595 and this bracket in turn supports the lower end of a vertical shaft 596 having adjacent its upper end a rock arm 597 which is connected by a link 598 with the rock lever 564. Now referring as well to Figures 48 and 49, it will be seen that in the plate 594 there is a slot 599 and across this slot extends a shaft 600 whereon is a ratchet or star wheel 601 having four teeth. Adjacent this star wheel is a cam 602 which bears against a lug 603 fixed on a spring contact arm 604. The arrangement is such that the cam 602 has two high points and two low points so that turning the ratchet wheel one tooth moves the contact 604 from its normal position to its contacting position and on turning toward the second tooth a second contact is made. In other words, with each movement of one tooth of the ratchet a contact is temporarily made as will be presently understood. Alongside of the cam 602 is a cam 605 which has two high spots and two low spots and this cam lies behind a spring finger 606 which engages a vertical finger 607 so that the vertical finger is pushed to the left away from the plate 594 when the cam 605 lies with the high spot behind the finger 606. Accordingly, the movement of the ratchet 110 one tooth at a time alternately places the finger 607 to the left and allows it to fall back to its normal position at the right. Referring now to Figure 25 it will be seen that carried by the reversing switch is a 115 hook pawl 426 and this pawl is so positioned that the energization of the magnet 586 moves the four toothed ratchet 601 outwardly so that upon downward motion of the elevator partially past the record selector the 120 125 130 135 140 145 150 155 160 165 170 175 180 185 190 195 200 205 210 215 220 225 230 hook pawl 426 engages and rotates this ratchet one tooth. If, however, the magnet 586 be not energized and if the plate 594 has not been moved to the left, such engagement will not take place and the hook 426 will move freely downward past the ratchet 601. One side of the magnet 586 is connected by a wire 608 with the contact 165 of the first selector unit 142a. The other side of such magnet 586 is connected by a wire 609 with the wire 185' and consequently with the repeat and consecutive button 39 as previously described. It will be noted that the contact 168 does not complete the circuit until after 15 the first numeral of the number has been dialed and at such time the contact 168 will engage the contact 165 and keep in such engagement until the selector has been cleared either by the action of the clearing switch 20 or by the action of the emergency button. One side of the magnet 589 is connected to the wire 326 and thus to the battery positive 195 while the other side of said magnet is connected by a wire 610 with the wire 257 25 and thus to the second button 181 of the emergency switch. In the wiring diagram for purposes of convenience and to avoid confusion in the circuit 604 has been shown in one position, while the controlling magnets 586 and 589 has been shown in a different part of the diagram. It is however to be understood that these parts are of course together. This is clearly shown in the Figures 57 and 58. Fixed on the rod 596 30 is an insulating plate 611 on which is mounted a contact 612 and a contact 613. These contacts are so positioned that rocking of the rod 596 brings one or the other of these contacts into position to be engaged by the contact 604 when the same is moved under 35 the influence of the cam 601. The contact 612 is connected to a wire 614 with the magnet 202 while the contact 613 is connected by a wire 615 with the magnet 571. In the diagram the contact 604 is shown as connected to the negative side of the battery through a wire 616. In actual construction this contact is simply grounded on the negative rail 317.

It will now be understood that if the reversing button be pushed after the dialing is effected, then the magnet 586 will be energized and parts will be placed in position for the reversing movement. Under these circumstances, the elevator and selector go through their usual movement of selecting and elevating the record and the lateral carrier places the record on the turn table so that it is played and then removes it and 55 delivers it back to the elevator. Now the elevator passes downwardly and the finger 426 engages the ratchet 601 and makes contact with one or the other of the contacts 612 or 613 by the movement of the contact 604. Whichever one of these contacts is thus

engaged, results in that one of the magnets 202 and 571 being energized which shifts the switch point 371 from the position in which it is at the time of engagement to the opposite position and at the same time rocks the vertical shaft 596 to move the plate 611 and bring the other contact of the contacts 612 and 613 into position for engagement by the contact 604. At the same time the action of the ratchet wheel causes movement of the finger 607 to the left so that as the reversing switch moves somewhat further downwardly, the lug 306 engages the angular lower end of this finger 607 and the action of the switch is reversed. Thus, the elevator does not move down to its position for restoring the records to the rack, but on the contrary it reverses before it gets to this position and again rises, moving it to the other branch of the Y. The record will now be delivered to the turn 80 table with the opposite side upward and the second side of the record will be played after which it will be again delivered to the elevator and carried downwardly. As the elevator passes downwardly, the ratchet 601 will 85 be rotated a second tooth so that the finger 607 drops back to normal position and thus permits the passage of the elevator all the way down to the position for restoring the record to its rack. At the same time, a second engagement of the contact 604 with the remaining contact of the contact 612 and 613 is made and the plate 611 is again shifted, being restored this time to the position in which it originally occupied upon dialing. If this position is not the normal position of the plate 611, the action of the clearing or 90 four point switch at the close of operation will effect restoration of the plate 611 to its normal or rest position.

Emergency reverse for elevator

Just above the magnets last described, there is a pair of magnets 617 which act on an armature 618 mounted on a rock arm carried by the shaft 619 and on this shaft is a forwardly projecting arm 620 which carries a tumbling pawl 621 so arranged that when the magnet 617 is energized and the armature 618 attracted thereby, the pawl 621 will be moved into the path of the lug 306. Now this pawl is so arranged that it will move freely downward as the lug passes it, but will engage the lug upon upward movement and reverse the reversing switch. Consequently, if, after dialing and before the elevator has reached its uppermost position, the emergency button be pressed, the magnet 617 will be energized and the tumbling pawl 621 positioned for reversing the elevator. When the emergency button is pressed, this pawl is rocked out into position by a small dog 622 fixed on a shaft 623 and engaging a plate or finger 624 on the lower end of the shaft 619. This shaft 623 is provided with a rock 105

arm 625 carrying an armature 626 which is the armature for the magnet 627 forming the clearing magnet for this part of the device. One side of the magnet 617 is connected to the contact 181 of the emergency unit through the wire 257 while the other side of said magnet is connected to a wire 628 with the battery positive wire 195. One side of the magnet 627 is connected by the wire 629 with the four point switch or clearing switch while the other side of this magnet is connected by a wire 630 with one side of a magnet 631 which has its other side connected by a wire 632 with the wire 257 leading to the second emergency contact 181. This magnet 631 controls the release of the turn table motor switch and when energized permits movement of the turn table motor switch to "off" position.

20 *The motor starting and accessories*

In Figures 1A and 1B there will be seen the devices for controlling motor starting switch and also for handling the arm and reproducer as well as certain other parts. At 634 is shown the ordinary motor starting switch such as is commonly used on ordinary phonographs and it is not deemed necessary to go into all of the details regarding the construction of this switch as the particular structure thereof forms no part of the present invention. The attachments or changes necessary in order to make this switch operate with the present invention will be described, however, in particular detail. Also, there will be set forth a supplemental attachment by means of which other records than the ordinary records may be played on the machine, so that the machine is universal in the handling of records. In the ordinary construction of the switch and stop 634, a handle projects from one of the moving parts at the point 635 but in the present instance it is found advisable to cut the handle off at this point and place beneath the turn table, a pivot plate 636 whereto is pivoted a long handle 637 which is connected to the stub of the handle where it is cut off by a link 638. Projecting from the pivoted portion of the handle 637 is an arm 639 so that the handle and this arm form a bell crank lever. Pivoted to a plate 640 is a double armed trip lever 641, one arm of which engages an extension piece 642 fixed to the operating part of the switch 634 so that as the arm 642 is rocked, the handle 637 will be moved in accordance therewith. This arm 642 is rocked to the right of Figure 1B in starting the motor and consequently the handle 637 will be moved to the left for the "on" position. In order to operate the lever 641 and therefore the lever 642 there is connected to the other arm of the lever 641 a reach rod 643 which extends diagonally across beneath the turn table and has its end fixed on a rock-

arm 644 by means of a suitable pivot pin. This rock arm 644 is carried on a rock shaft 645 and on the upper end of this rock shaft is a rock arm 646 which is pivoted to a pusher element 647 having a slot 648 therein which travels on a pin 649. Fixed on the primary frame of the traversing carrier is a lug 650 which on the first travel of the carrier to the right in placing the record on the turn table, engages the member 648 and pushes on the same so that the rock shaft 645 is rocked and the rock arm 644 moved to pull on the links or connecting rod 643. This of course, swings the lever 641 which in turn swings the arm 642 and turns the switch for the turn table motor on, at the same time moving the handle from the "off" to the "on" position. As will be hereinafter understood, provision is made, when the record has been played, for the stoppage of the turn table motor and accordingly provision is made for the non-operative positioning of the member 647 when the carrier moves to the right the second time to take the record off of the turn table. To this end, the bracket 651 supports a shaft 652 and on this bracket is mounted an arm 653 which carries on its free end the pin 649, the arm being pivoted at its other end. On the shaft 652 is mounted a cam having two high and two low points, this cam being shown at 654. Also, on this shaft is fixed a fourth toothed ratchet 655 which is positioned to be engaged by a spring pressed hook pawl 656 supported on a suitable bracket from the upper or secondary carrier frame. As the first movement of the carrier to the right takes place, the pawl 656 rides over the ratchet 655 and upon the return of the carrier, returns the ratchet and the cam 654 through one quarter of a revolution or from the high to the low point. This effects swinging of the push member 648 out of the path of the lug 650 so that on the second return of the carrier, no operation of the motor switch 634 is effected. The motor switch is provided with the usual latching dog 657 which, when it engages the rotating part of the switch, holds the switch releasably in "on" position. This switch is connected by an arm 658 with the armature 659 of the emergency motor release magnet 631 so that pressing the emergency button, as previously described, after the turn table is in motion, will stop the motion of the turn table by throwing the switch 634 to "off" position. At 660 is a plate whereon is slidably mounted a bar 661 which has its free end connected to the switch 139 for purposes which will presently be described. On the plate 660 is furthermore pivoted one end of a lever 662 which is connected by a link 663 with one arm of a bell crank lever 664 pivoted on a plate 665 and having its other arm connected by the link 666 with the end of the lever 641 opposite that which engages the finger or arm 642. Carried by the bar 661

but insulated therefrom is a contact member 667 which normally engages a fixed contact 668 as shown in Figure 1A. Below the path of the tone arm is positioned a vertical plate 5 of insulation 669 best shown in Figure 63. This block has a top edge 670 whereon the tone arm normally rests and just below this top edge there is pivoted an arm 671 which carries an insulating block 672 positioned to be engaged by a finger 673 depending from the tone arm when the latter is in rest position so that the arm 671 is depressed. This arm carries a spring contact member 674 which is positioned to engage a fixed contact 10 675 upon the tone arm moving off of the block 672 and the arm 671 being raised by the spring 676. Also mounted on this block 672 is a pair of spring fingers 677 having converging terminal ends which fit between contacts 15 678. The forward edge of the plate 670 drops off as at 679 and projecting from this edge 679 is an arm 680 of insulating material, the arm normally being held raised by the spring 676 and in such position that it will not be engaged by the fingers 673 if the needle of the 20 reproducer, in the downward movement, of the tone arm, contacts with a record on the turn table. However, this arm 680 is high enough so that it is depressed by the finger 25 673 if there is no record on the turn table and the tone arm is allowed to drop below its normal record playing position. The arm 680 carries a movable contact member 681 which, when the arm is depressed, engages a fixed 30 contact 682. The contact 675 is connected with the contact 667, see the diagram, by a wire 683. The contact 668 is connected by a wire 684 with the B negative wire 206 and contact 682 is also connected through this wire 35 40 to the B negative. The contact 681 is connected by a wire 685 with the wire 257 leading to the emergency contact 181. Finally the contact 674 is connected by a wire 686 with the reproducer lift magnet 687 which 45 is in turn connected to the wire 330 by wire 688 leading to the green light. It will be remembered that the wires 196 and 194 which give battery positive current to the selector units 142a and 142b are connected to the contacts 677 and 678 so that the tone arm in its 50 position of rest holds these contacts closed and thus enables current to be provided to these selector units but, when the tone arm moves into active position, the circuit is 55 broken at this point and these selector units are no longer provided with battery positive current through these wires.

Now normally, the contacts 668 and 667 are closed thus when the push member 648 is 60 pushed to the right, these contacts will be open. Under these circumstances, contacts 667 and 668 being opened as well as contacts 674 and 675, the circuit through the magnet 687 is broken at two places. When the tone 65 arm moves into operative position in playing

the record, then the contact 674 will engage the contact 675 and this contact will establish circuit so far as this particular point is concerned. However, the breaking of the contact at 667 and 668 will still leave this circuit open and it is not until the playing of the record has been concluded or the emergency button pressed that these contacts 667 and 668 will engage and thus establish complete circuit through the magnet 687 and thus operate the lifting device for the tone arm. Adjacent the member 661 is pivoted a latch 689 which, when the member 661 is pushed to the right, engages a notch in that member and holds it in that position and in order to permit lever 641 and certain other parts to resume their normal position after the operation of the push bar 648, the lever 662 is not pivoted to the member 661 but merely pushes against the stop 690 on that part. Now the latch 689 has an operating arm 691 which lies in the path of the end of a push rod 692 which is pivoted to the arm 639 on the switch handle 637. When the switch is in the "off" position, the push rod 692 pushes on the rod 691 and frees the latch 689 from its notch, but when the switch is in the "on" position, then the latch 689 is free to drop into the notch. Now when the record reaches the end of its play, then the switch naturally is moved to "off" position by the mechanism 634 and contact is allowed to be made between the contact 667 and 668 by the movement of the bar 661 to the left. Mounted adjacent the magnet 687 is a rock shaft 693 on which is mounted a shaft 100 crank rock arm, having a short upwardly extending end provided with an armature 694 for said magnet. The other end projects forwardly and carries an arcuate member 695 having an inclined upper surface. Swiveled on a post 696 is an arm 697 having a slot 698 in its end which receives the pin of the finger 673 projecting downwardly from the tone arm 699. This arm 697 is so positioned that when the magnet 687 is energized and the arcuate member 695 raised, this member will engage beneath the arm 697 and lift that arm. At this time, the tone arm is shifted to such height that the finger 673 lies slightly above the edge 670 of the plate 669. It is of course to be understood that this lifting action only takes place when the tone arm has dropped off of the plate 669. Now when the tone arm is in this position, the movement of the carrier to the right will engage the reproducer unit and push the tone arm to the left around the arcuate member 695 so that it swings to its position of rest and at the same time drops slightly downward to engage on the top edge 670 and thus depress the lock 672 and opens the contact 674 which de-energizes the magnet 687.

The tone arm 699 is provided with the usual downwardly extending pin 700 which engages between the arms of a fork 701 forming 120

part of the switch mechanism 634 and for the purposes of this invention, there is provided a small spring pressed arm 702 which acts, when the tone arm moves to first engage the 5 record, to throw the needle into engagement with the first groove of the record.

Connected to the bell crank arm is a link 703, which, see Figure 65, is connected to a rock arm 704, mounted on a sleeve 705 supported on a vertical shaft 706. Also, on the sleeve 705 is an arm 707 having an upturned end 708 and pivoted to this arm is a finger 709 which is normally held in vertical position by a weight 710, but which will tilt to allow positioning of a rib 711 projecting downwardly from the arm 697 to engage between this finger and the end 708. In the operation of this part of the device, we may assume that the tone arm 699 is in its position of rest. 10 Then when the push bar 648 is moved, the link 703 will be moved to rock the arm 704 and thus in turn will rock the arm 707 so that the rib 711 will engage between the end 708 and finger 709. Now, when the pressure is released on the push bar 648 in the return of the carrier to the position of rest, the link 703 will be pulled to swing the arms 704 and 707 to their normal position and at this time, the finger 709 will push against the plate 711 and 15 thus push the tone arm supporting finger 673 off of the plate 669 and, under normal position, allow the needle to drop on the record. It will be noted that the plate 711 is of such length that at the end of the pushing movement of the finger 709 this finger slips off the right end of the plate 711 as shown in Figure 64, thus allowing the tone arm to move freely across the record in its play.

It will be remembered that the switch 139 20 controls the circuit through the magnet 133 which operates the double pole or mercury switch for closing the circuit through the motor 95 operating the various parts of the invention. Now normally this switch is closed and as will be seen from Figures 5A, 59 and 60, this switch consists of two insulating plates 712 and 713 which are supported on a fixed pivot 714 so that these plates may rock together or independently. Normally, the spring 715 holds them to rock together and plate 712 is connected to the bar 661 and operates with the operation of that bar. The normal position of these parts is shown in Figure 5A but when the bar 661 25 is moved and latched as takes place toward the end of the movement of the lateral carrier to the right, then the switch 139 will be rocked to the position shown in Figure 59, a lug or projection 716 on the carrier having moved past this switch. It will be noted that the upper end of the arm 713 is provided with a cam plate 717 which in the position shown in Figure 59 lies in the path of the lug 716. When the record has been placed on the turn 30 table and the carrier moves back to its inter-

mediate position, it is then, of course, necessary to stop the motor 95 and at this time, the lug or projection 716 engages the cam surface 717 and moves the arm 713 of the switch away from the arm 712. Now the arm 712 carries a contact 718 and the arm 713 carries a similar contact 719 so that by movement of the arm to the position shown in Figure 60 these contacts are opened, and thus the circuit through the magnet 133 is broken 75 and as a consequence the motor circuit is broken and the motor stopped. When the record has been completely played or when the emergency button is pushed, it is again necessary to close this circuit and the movement of the bar 661 to the left will restore the parts to the position shown in Figure 5A and consequently close the circuit so that the motor 95 will start up for the balance of the movement of the apparatus. 80 85

Consecutive record playing

It will be remembered that a relay is provided in connection with the selector unit 142c and that this relay regulates the position of a contact 190 with respect to contact 189 and 188. Now normally contact 188 is in engagement with the contact 190 as previously described but when the relay is energized, the contact 190 will be locked in engagement with the contact 189 and from this contact a wire 720 leads to a magnet 721 controlling a movable contact 722 so that energization of this magnet brings the movable contact into engagement with a fixed contact 723. The magnet 721 is connected to the wire 241 and thus to the arm 177 of the selector unit 142d. The contact 722 is connected by a wire 724 with the B-negative wire 206 and the contact 723 is connected by wire 725 with the wire 230 leading to the operating magnet 150d for the arm 177. It will be remembered that it has been explained that when the record selector is rocked in position on the vertical rails 317 and 318 the current through the magnet 238 is broken by the contact 235 and 236 dropping slightly below the energized contact 233 and 227. Now when the magnet 721 closes the contact 722 to 723 then the current will flow through the magnet 150d and thus step up the arm 177 one point. The selected record will then be carried up and played and after it is put away in the rack and the elevator moves to return with the record selector in this descent, the contact fingers 233 and 236 will engage the next lower contact 233 and 227. The stepping up of the arm 177 has energized this next pair of fixed contacts and consequently on reaching these contacts the magnet 238 will be energized and the record selector rocked to the next lower pair of notches, the elevator descending as usual and picking out the next lower record. Thus, on the downward movement to select each record, the arm 177 is 100 105 110 115 120 125 130

stepped up one point and the operation is repeated throughout the entire set of records unless dropped sooner by operating the emergency button.

5 *Checking device at the transfer point.*

In order to slow up the action of the motor during the time when the record is transferred between the elevator and the laterally movable carrier, a certain auxiliary braking mechanism is employed. By reference to Figure 4B it will be seen that there is pivoted to the motor frame a governor control arm 726 which rocks the shaft 727 whereon is mounted the governor brake 728. This arm 726 is connected to the plunger 729 of a solenoid 730. A wire 371, see Figure 66a, connects this solenoid to the positive side of the battery and from the solenoid wire 732 extends to the member 356 so that when the rollers 332 and 334 engage this member 356 the solenoid is energized and the motor slowed down and it is to be observed that this engagement takes place both on the upward movement of the carriage and on the downward movement thereof.

The operation having been first described in general and then each specific operation having been particularly described, it is not deemed necessary here to again set forth a general description of the operations, of which the invention is capable, but it is merely deemed necessary to say that there has just been provided a simple and highly efficient device of the kind described and specified.

It is obvious that many minor changes may be made in the form and construction of the invention without departing from the material principles thereof. It is not therefore desired to confine the invention to the exact form herein shown and described, but it is wished to include all forms such as properly come within the scope claimed.

45 Having thus described the invention, what is claimed as new, is:

1. In an attachment for phonographs, a record rack, a gripper mounted for movement past records held in said rack, means to cause said gripper to grasp a selected record, a carrier mounted for movement over and away from the record table of the phonograph, means to guide the gripper into position to deliver a record gripped to the carrier and to receive a record from the carrier, and motor means for successively operating the gripper and the carrier.

2. In an attachment for phonographs, a record rack, a gripping device mounted for movement past records in said rack, a gripper guide mounted for movement past said records, means for selectively positioning the guide to cause the gripper to engage a selected record in the rack, a carrier mounted

table of the phonograph, means to move the gripper into guide engaging position to grasp a record and into position to deliver the record to and receive it from the carrier, and motor means for successively operating the gripper and carrier. 70

3. In an attachment for phonographs, a record rack, a gripper mounted for movement past records held in said rack, means to cause said gripper to grasp a selected record, a carrier mounted for movement over and away from the record table of the phonograph, means to guide the gripper selectively into delivery positions to deliver a record with a selected side uppermost to the carrier and to receive a record from the carrier, and motor means for successively operating the gripper and the carrier. 80

4. In an attachment for phonographs, a record rack, a gripping device mounted for movement past records in said rack, a gripper guide mounted for movement past said records, means for selectively positioning the guide to cause the gripper to engage a selected record in the rack, a carrier mounted for movement over and away from the record table of the phonograph, means to move the gripper into guide engaging position to grasp a record and into selected position to deliver the record to and receive it from the carrier with a selected side uppermost, and motor means for successively operating the gripper and carrier. 90

5. In an attachment for turn table and reproducer provided phonographs, a pair of record racks arranged in parallelism, a selector movable between said racks past the records therein, a gripper between said racks and movable past the records therein, guide means carried by the selector to guide the gripper into gripping position relative to a selected rack, means to actuate the guide means, means to position the selector in selective relation to the records in said racks, and means to operate the gripper and cause it to grasp and withdraw the selected record from the rack and move said record into position for delivering a record to a record carrier. 100

6. In an attachment for turn table and reproducer provided phonographs, a pair of record racks arranged in parallelism, a selector movable between said racks past the records therein, a gripper between said racks and movable past the records therein, guide means carried by the selector to guide the gripper into gripping position relative to a selected rack, means to actuate the guide means, means to position the selector in selective relation to the records in said racks, means to operate the gripper and cause it to grasp and withdraw the selected record from the rack and move said record into position for delivering a record to a record carrier, a record carrier movable between position to receive and deliver records from and to the 110

- gripper and position to deliver and receive records to and from the phonograph turn table, and means to cause said carrier to receive a record from the gripper and deliver it to the turn table. 5 of the phonograph in completing the playing of the record and arranged to cause forward movement of the carrier moving means.
7. In an attachment for turn table and reproducer provided phonographs, a pair of record racks arranged in parallelism, a selector movable between said racks past the records therein, a gripper between said racks and movable past the records therein, guide means carried by the selector to guide the gripper into gripping position relative to a selected rack, means to actuate the guide means, means to position the selector in selective relation to the records in said racks, means to operate the gripper and cause it to grasp and withdraw the selected record from the rack and move said record into position 10 for delivering a record to a record carrier, a record carrier movable between position to receive and deliver records from and to the gripper and position to deliver and receive records to and from the phonograph turn table, means to cause said carrier to receive a record from the gripper and deliver it to the turn table, means actuated by the completion of the forward motion of the carrier for reversing the operation of the last mentioned means to cause partial retraction of the carrier, and means actuated by the completion of the partial retraction of the carrier to cause operation of the turn table and positioning of the reproducer on the record 15 on said turn table. 20
8. In an attachment for turn table and reproducer provided phonographs, a pair of record racks arranged in parallelism, a selector movable between said racks past the records therein, a gripper between said racks and movable past the records therein, guide means carried by the selector to guide the gripper into gripping position relative to a selected rack, means to actuate the guide means, means to position the selector in selective relation to the records in said racks, means to operate the gripper and cause it to grasp and withdraw the selected record from the rack and move said record into position for delivering 25 a record to a record carrier, a record carrier movable between position to receive and deliver records from and to the gripper and position to deliver and receive records to and from the phonograph turn table, means to cause said carrier to receive a record from the gripper and deliver it to the turn table, means actuated by the completion of the forward motion of the carrier for reversing the operation of the last mentioned means to cause partial retraction of the carrier, means actuated by the completion of the partial retraction of the carrier to cause operation of the turn table and positioning of the reproducer on the record on said turn table, other means caused to operate by the action 30 of the phonograph in completing the playing of the record and arranged to cause forward movement of the carrier moving means. 35
9. The combination with an automatic phonograph having a magazine of records, of a selecting mechanism electrically controlled at a remote distance from the machine for selectively arranging and playing a selected side of any desired record and subsequently returning it to its inactive position. 40
10. The combination with an automatic phonograph having a magazine of records, of a selecting mechanism electrically controlled at a remote distance from the machine for selectively arranging and playing both sides of any desired record and subsequently returning it to its inactive position. 45
11. The combination with an automatic phonograph having a magazine of records, of a selecting mechanism electrically controlled at a remote distance from the machine for selectively arranging and playing both sides of a series of records and returning each after playing to its initial position. 50
12. The combination with an automatic phonograph having a magazine of records, of a selecting mechanism electrically controlled at a remote distance from the machine for selectively arranging and playing selected sides of a series of records and returning each after playing to its initial position. 55
13. The combination with an automatic phonograph having a magazine of records, of a selecting mechanism electrically controlled at a remote distance from the machine for selectively arranging and playing a series of records in succession beginning with any desired record in the magazine and returning each after playing to its initial position. 60
14. The combination with an automatic phonograph having a magazine of records, of a selecting mechanism electrically controlled at a remote distance from the machine for selectively arranging and playing a selected side of any desired record and subsequently returning it to its inactive position, and means associated with said remote control for causing the selecting mechanism to repeat the playing of the selected record at will. 65
15. The combination with an automatic phonograph having a magazine of records, of a selecting mechanism electrically controlled at a remote distance from the machine for selectively arranging and playing both sides of any desired record and subsequently returning it to its inactive position, and means associated with said remote control for causing the selecting mechanism to repeat the playing of either side of the selected record at will. 70
16. The combination with an automatic phonograph having a magazine of records, 75

- of a selecting mechanism electrically controlled at a remote distance from the machine for selectively arranging and playing both sides of a series of records and returning each 5 after playing to its initial position, and means associated with said remote control for causing the selecting mechanism to repeat the playing of a selected side of a selected record of said series.
- 10 17. The combination with an automatic phonograph having a magazine of records, of a selecting mechanism electrically controlled at a remote distance from the machine for selectively arranging and playing selected 15 sides of a series of records and returning each after playing to its initial position, and means associated with said remote control for causing the selecting mechanism to repeat the playing of a selected record of said 20 series.
18. The combination with an automatic phonograph having a magazine of records, of a selecting mechanism electrically controlled at a remote distance from the machine for selectively arranging and playing a series of records in succession beginning with any desired record in the magazine and returning each after playing to its initial position, and means associated with said remote 25 control for causing the selecting mechanism to repeat the playing of a selected record of said series.
19. The combination with an automatic phonograph having a magazine of records, of a selecting mechanism electrically controlled at a remote distance from the machine for selectively arranging and playing a selected side of any desired record and subsequently returning it to its inactive position, and means associated with said remote 30 control for causing the action of the selecting mechanism to be reversed prior to beginning the playing of the record and the record to be restored to its initial position without playing.
- 40 20. The combination with an automatic phonograph having a magazine of records, of a selecting mechanism electrically controlled at a remote distance from the machine for selectively arranging and playing both sides of any desired record and subsequently returning it to its inactive position, and means associated with said remote control for causing the action of the selecting mechanism to be reversed prior to beginning the playing of a selected side of the record and the record to be restored to its initial position without playing.
- 45 21. The combination with an automatic phonograph having a magazine of records, of a selecting mechanism electrically controlled at a remote distance from the machine for selectively arranging and playing both sides of a series of records and returning each after playing to its initial position, and
- means associated with said remote control for causing the action of the selecting mechanism to be reversed prior to beginning the playing of a selected side of a selected record of said series, the selected record to be restored to its initial position without playing and the playing of the series to cease. 75
22. The combination with an automatic phonograph having a magazine of records, of a selecting mechanism electrically controlled at a remote distance from the machine for selectively arranging and playing selected sides of a series of records and returning each after playing to its initial position, and means associated with said remote control for causing the action of the selecting mechanism to be reversed prior to beginning the playing of a selected record of said series, the selected record to be restored to its initial position without playing and the playing of the series to cease. 80
23. The combination with an automatic phonograph having a magazine of records, of a selecting mechanism electrically controlled at a remote distance from the machine for selectively arranging and playing a series of records in succession beginning with any desired record in the magazine and returning each after playing to its initial position, and means associated with said remote control for causing the action of the selecting mechanism to be reversed prior to beginning the playing of a selected record of said series, the selected record to be restored to its initial position without playing and the playing of the series to cease. 90
24. The combination with an automatic phonograph having a magazine of records, of a selecting mechanism electrically controlled at a remote distance from the machine for selectively arranging and playing a selected side of any desired record and subsequently returning it to its inactive position, and means associated with said remote control for causing the selecting mechanism to interrupt the playing of the selected record and restore it to its initial position without further playing of said record. 100
25. The combination with an automatic phonograph having a magazine of records, of a selecting mechanism electrically controlled at a remote distance from the machine for selectively arranging and playing both sides of a series of records and returning each after playing to its initial position, and means associated with said remote control for causing the selecting mechanism to interrupt the playing of a selected record of the series and restore it to its initial position without further playing of said records. 115
26. The combination with an automatic phonograph having a magazine of records, of a selecting mechanism electrically controlled at a remote distance from the machine for selectively arranging and playing

selected sides of a series of records and returning each after playing to its initial position, and means associated with said remote control for causing the selecting mechanism to interrupt the playing of a selected record of the series and restore it to its initial position without further playing of said records.

27. The combination with an automatic phonograph having a magazine of records, of a selecting mechanism electrically controlled at a remote distance from the machine for selectively arranging and playing a series of records in succession beginning with any desired record in the magazine and returning each after playing to its initial position, and means associated with said remote control for causing the selecting mechanism to interrupt the playing of a selected record of the series and restore it to its initial position without further playing of said records.

28. The combination with an automatic phonograph having a magazine of records, of a selecting mechanism electrically controlled at a remote distance from the machine for selectively arranging and playing a selected side of any desired record and subsequently returning it to its inactive position, means associated with said remote control for causing the selecting mechanism to repeat the playing of the selected record at will, and means associated with said remote control for causing the selecting mechanism to interrupt the playing of the selected record and restore it to its initial position without further playing of said record.

29. The combination with an automatic phonograph having a magazine of records, of a selecting mechanism electrically controlled at a remote distance from the machine for selectively arranging and playing both sides of any desired record and subsequently returning it to its inactive position, means associated with said remote control for causing the selecting mechanism to repeat the playing of either side of the selected record at will, and means associated with said remote control for causing the selecting mechanism to interrupt the playing of the selected record and restore it to its initial position without further playing of said record.

30. The combination with an automatic phonograph having a magazine of records, of a selecting mechanism electrically controlled at a remote distance from the machine for selectively arranging and playing both sides of a series of records and returning each after playing to its initial position, means associated with said remote control for causing the selecting mechanism to repeat the playing of a selected side of a selected record of said series, and means associated with said remote control for causing the playing of a selected record of the series and

restore it to its initial position without further playing of said record.

31. The combination with an automatic phonograph having a magazine of records, of a selecting mechanism electrically controlled at a remote distance from the machine for selectively arranging and playing selected sides of a series of records and returning each after playing to its initial position, means associated with said remote control for causing the selecting mechanism to repeat the playing of a selected record of said series, and means associated with said remote control for causing the selecting mechanism to interrupt the playing of a selected record of the series and restore it to its initial position without further playing of said records.

32. The combination with an automatic phonograph having a magazine of records, of a selecting mechanism electrically controlled at a remote distance from the machine for selectively arranging and playing a series of records in succession beginning with any desired record in the magazine and returning each after playing to its initial position, means associated with said remote control for causing the selecting mechanism to repeat the playing of a selected record of said series, and means associated with said remote control for causing the selecting mechanism to interrupt the playing of a selected record of the series and restore it to its initial position without further playing of said records.

33. The combination with an automatic phonograph having a magazine of records, of a selecting mechanism electrically controlled at a remote distance from the machine for selectively arranging and playing a selected side of any desired record and subsequently returning it to its inactive position, means associated with said remote control for causing the selecting mechanism to repeat the playing of the selected record at will, and means associated with said remote control for causing the action of the selecting mechanism to be reversed prior to beginning the playing of the record and the record to be restored to its initial position without playing.

34. The combination with an automatic phonograph having a magazine of records, of a selecting mechanism electrically controlled at a remote distance from the machine for selectively arranging and playing both sides of any desired record and subsequently returning it to its inactive position, means associated with said remote control for causing the selecting mechanism to repeat the playing of either side of the selected record at will, and means associated with said remote control for causing the action of the selecting mechanism to be reversed prior to beginning the playing of a selected

side of the record and the record to be restored to its initial position without playing.

35. The combination with an automatic phonograph having a magazine of records, of a selecting mechanism electrically controlled at a remote distance from the machine for selectively arranging and playing both sides of a series of records and returning each after playing to its initial position, means associated with said remote control for causing the selecting mechanism to repeat the playing of a selected side of a selected record of said series, and means associated with said remote control for causing the action of the selecting mechanism to be reversed prior to beginning the playing of a selected side of a selected record of said series, the selected record to be restored to its initial position without playing and the playing of the series to cease.

36. The combination with an automatic phonograph having a magazine of records, of a selecting mechanism electrically controlled at a remote distance from the machine for selectively arranging and playing selected sides of a series of records and returning each after playing to its initial position, means associated with said remote control for causing the selecting mechanism to repeat the playing of a selected record of said series, and means associated with said remote control for causing the action of the selecting mechanism to be reversed prior to beginning the playing of a selected record of said series, the selected record to be restored to its initial position without playing and the playing of the series to cease.

37. The combination with an automatic phonograph having a magazine of records, of a selecting mechanism electrically controlled at a remote distance from the machine for selectively arranging and playing a series of records in succession beginning with any desired record in the magazine and returning each after playing to its initial position, means associated with said remote control for causing the selecting mechanism to repeat the playing of a selected record of said series, and means associated with said remote control for causing the action of the selecting mechanism to be reversed prior to beginning of the playing of a selected record of said series, the selected record to be restored to its initial position without playing and the playing of the series to cease.

38. The combination with an automatic phonograph having a distantly positioned controlling dial and a controlled emergency circuit whereby correction in a dialed number may be effected.

39. The combination with an automatic phonograph having a distantly positioned controlling dial and volume controlling mechanism for the phonograph adapted

itself for control by manipulation of the dial.

40. The combination with an automatic phonograph having record selecting mechanism and a controlling dial therefor, means adapted upon the dialing of a wrong number to automatically return the parts to normal.

41. The combination with an automatic phonograph having an operator's station and means for signalling at such station conditions existing in the mechanism of the phonograph.

42. The combination with a disk playing phonograph having a turn table; of a disk record magazine adapted to receive double faced records, and a record carrying mechanism arranged to select a record from said magazine and place it on the turn table with a side selected by the carrying mechanism in playing position.

43. The combination with a disk playing phonograph having a turn table; of a disk record magazine adapted to receive double faced records, and a record carrying mechanism arranged to select a record from said magazine and place it on the turn table with a side selected by the carrying mechanism in playing position, and means to reverse the action of said mechanism upon completion of the playing of the record whereby to remove the record from the turn table and restore it to the magazine.

44. The combination with a disk playing phonograph having a turn table; of a disk record magazine adapted to receive double faced records, and a record carrying mechanism arranged to select a record from said magazine and place it on the turn table with a side selected by the carrying mechanism in playing position, and means to reverse the action of said mechanism at a desired point in the playing of the record whereby to remove the record from the turntable and restore it to the cabinet.

45. The combination with a disk playing phonograph having a turn table; of a disk record magazine adapted to receive doubled faced records, and a record carrying mechanism arranged to select a record from said magazine and place it on the turn table with a side selected by the carrying mechanism in playing position, and means to reverse the action of said mechanism automatically actuated upon completion of the playing of the record whereby to remove the record from the turntable and restore it to the magazine.

46. The combination with a disk playing phonograph having a turntable; of a record magazine, means operating to select a record from the magazine and place it on the turntable, controlling mechanism operable to cause said means to remove and replace said record on the turntable with the sides reversed in position, and other controlling mechanism operable to cause restoration of the record to the cabinet in normal position.

47. The combination with a disk playing phonograph having a turntable; of a record magazine, means operating to select a record from the magazine and place it on the turntable, controlling mechanism operable to cause said means to remove and replace said record on the turntable with the sides reversed in position, other controlling mechanism operable to cause restoration of the record to the cabinet in normal position, at any time in the playing of the record at the will of the operator. 70
- 10 record to the cabinet in normal position, and means controlled by the completion of the playing of the record and automatically effecting actuation of the last mentioned controlling mechanism. 75
- 15 48. The combination with a disk playing phonograph having a turntable; of a record magazine, means operating to select a record from the magazine and place it on the turntable, controlling mechanism operable to cause said means to remove and replace said record on the turntable with the sides reversed in position, other controlling mechanism operable to cause restoration of the record to the cabinet in normal position, means controlled by the completion of the playing of the record and automatically effecting actuation of the last mentioned controlling mechanism, and other means controlled by the operator and also effecting actuation of said last mentioned controlling means. 80
- 20 49. The combination with a disk playing phonograph having a turntable; of a record magazine, means operating to select a record from the magazine and place it on the turntable, and controlling mechanism operable to cause said means to remove and replace said record on the turntable with the sides in the same position to effect repetition of the playing of the record. 85
- 25 50. The combination with a disk playing phonograph having a turntable; of a record magazine, means operating to select a record from the magazine and place it on the turntable, and controlling mechanism operable to cause said record on the turntable with the sides in the same position to effect repetition of the playing of the record, other controlling mechanism operable to cause restoration of the record to the cabinet in normal position. 90
- 30 51. The combination with a disk playing phonograph having a turntable; of a record magazine, means operating to select a record from the magazine and place it on the turntable, and controlling mechanism operable to cause said record on the turntable with the sides in the same position to effect repetition of the playing of the record, other controlling mechanism operable to cause restoration of the record to the cabinet in normal position. 95
- 35 52. The combination with a disk playing phonograph having a turntable; of a record magazine, means operating to select a record from the magazine and place it on the turntable, and controlling mechanism operable to cause said record on the turntable with the sides in the same position to effect repetition of the playing of the record, other controlling mechanism operable to cause restoration of the record to the cabinet in normal position, means controlled by the completion of the playing of the record and automatically effecting actuation of the last mentioned controlling mechanism, and other means controlled by the operator and also effecting actuation of said last mentioned controlling means. 100
- 40 53. The combination with a disk playing phonograph having a turntable; of a record magazine, means operating to select a record from the magazine and place it on the turntable, and controlling mechanism operable to cause said record on the turntable with the sides in the same position to effect repetition of the playing of the record, other controlling mechanism operable to cause restoration of the record to the cabinet in normal position, means controlled by the completion of the playing of the record and automatically effecting actuation of the last mentioned controlling mechanism, and other means controlled by the operator and also effecting actuation of said last mentioned controlling means. 105
- 45 54. The combination with a disk playing phonograph having a turntable; of a record magazine, means operating to select a record from the magazine and place it on the turntable, and controlling mechanism operable to cause said record on the turntable with the sides in the same position to effect repetition of the playing of the record, other controlling mechanism operable to cause restoration of the record to the cabinet in normal position, means controlled by the completion of the playing of the record and automatically effecting actuation of the last mentioned controlling mechanism, and other means controlled by the operator and also effecting actuation of said last mentioned controlling means. 110
- 50 55. The combination with a disk playing phonograph having a turntable; of a record magazine, a record selector selectively positionable before said magazine, record handling mechanism movable to operate separately from and controlled by the selector for taking a selected record from its magazine and delivering it to the turntable, control means for the handling mechanism operable to cause reverse action of the handling mechanism to restore the selected record to its place in the magazine, and means to cause automatic actuation of said control means upon completion of the playing of the selected record. 115
- 55 56. The combination with a disk playing phonograph having a turntable; of a record magazine adapted to receive double faced records, a record selector selectively positionable before said magazine, and record handling mechanism controlled by the selec- 120
- 60 at any time in the playing of the record at the will of the operator. 125
- 65 57. The combination with a disk playing phonograph having a turntable; of a record magazine, means operating to select a record from the magazine and place it on the turn- 130

tor for taking a selected record from its magazine and delivering it to the turntable, with a side selected by the carrying mechanism in playing position.

57. The combination with a disk playing phonograph having a turntable; of a record magazine adapted to receive double faced records, a record selector selectively positionable before said magazine, record handling mechanism controlled by the selector for taking a selected record from its magazine and delivering it to the turntable, with a side selected by the carrying mechanism in playing position, and control means for the handling mechanism operable to cause reverse action of the handling mechanism to restore the selected record to its place in the magazine.

58. The combination with a disk playing phonograph having a turntable; of a record magazine adapted to receive double faced records, a record selector selectively positionable before said magazine, record handling mechanism controlled by the selector for taking a selected record from its magazine and delivering it to the turntable, with a side selected by the carrying mechanism in playing position, control means for the handling mechanism operable to cause reverse action of the handling mechanism to restore the selected record to its place in the magazine, and means to cause automatic actuation of said control means upon completion of the playing of the selected record.

59. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, and control means for the handling mechanism operable to cause the handling mechanism to remove the record from the turntable and invert and replace said record on said turntable.

60. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, con-

trol means for the handling mechanism operable to cause the handling mechanism to remove the record from the turntable and invert and replace said record on said turntable, and means to cause actuation of said control means automatically upon completion of the playing of the first side of the record.

61. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, control means for the handling mechanism operable to cause the handling mechanism to remove the record from the turntable and invert and replace said record on said turntable, and other control means for said handling mechanism operable to cause the handling mechanism to remove the record from the turntable and replace it on the magazine in normal position.

62. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, control means for the handling mechanism operable to cause the handling mechanism to remove the record from the turntable and invert and replace said record on said turntable, other control means for said handling mechanism operable to cause the handling mechanism to remove the record from the turntable and replace it on the magazine in normal position, and means to cause actuation of said last control means automatically upon completion of the playing of the second side of the record.

63. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record,

the record handling mechanism being released from the selector upon the latter being moved to record selecting position, and control means for the handling mechanism operable to cause the handling mechanism to effect repetition of the playing of the record prior to its restoration to the cabinet.

64. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, control means for the handling mechanism operable to cause the handling mechanism to effect repetition of the playing of the record prior to its restoration to the cabinet, and means to cause actuation of said control means automatically upon completion of playing of the record the first time.

65. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, control means for the handling mechanism operable to cause the handling mechanism to effect repetition of the playing of the record prior to its restoration to the cabinet, means to cause actuation of said control means automatically upon completion of playing of the record the first time, and other control means for said handling mechanism operable to cause the handling mechanism to remove the record from the turntable and replace it in the magazine in normal position.

66. The combination with a disk playing phonograph having a turntable; of a record magazine, a record selector selectively positionable before said magazine, a record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, control means for the handling mechanism operable

to cause the handling mechanism to effect repetition of the playing of the record prior to its restoration to the cabinet, means to cause actuation of said control means automatically upon completion of playing of the record the first time, other control means for said handling mechanism operable to cause the handling mechanism to remove the record from the turntable and replace it in the magazine in normal position, and means to cause actuation of said last control means automatically upon completion of the playing of the record the last time.

67. In an automatic phonograph having a magazine of records adopted to receive double faced records, a selecting and playing mechanism for selecting a record from the magazine and playing a side selected by the carrying mechanism thereof and subsequently returning the record to the magazine.

68. In an automatic phonograph having a magazine of records, a selecting and playing mechanism for selecting a record from the magazine and playing both sides thereof and subsequently returning the record to the magazine, the mechanism being arranged to primarily play a selected side of the record.

69. In an automatic phonograph having a magazine of records, a selecting and playing mechanism for selecting a series of records from the magazine, playing both sides of each record and subsequently returning the records to normal positions in the magazine, the mechanism being arranged to primarily play a selected side of the record.

70. In an automatic phonograph having a magazine of records, a selecting and playing mechanism for selecting a series of records from the magazine, playing selected sides of each record and subsequently returning the records to normal positions in the magazine.

71. The combination with a disk playing phonograph having a turntable; of a record magazine, means operating to select a record from the magazine and place it on the turntable, controlling mechanism operable to cause said means to remove and replace said record on the turntable with the sides reversed in position, other controlling mechanism operable to cause restoration of the record to the cabinet in normal position, and means to cause successive alternate action of said first and second controlling means on successive records in the magazine.

72. The combination with a disk playing phonograph having a turntable; of a disk record magazine adapted to receive double faced records, and a record carrying mechanism arranged to select a record from said magazine and place it on the turntable with a side selected by the carrying mechanism in playing position, and electro-magnetic means to reverse the action of said mechanism upon completion of the playing of the record.

record whereby to remove the record from the turntable and restore it to the magazine.

73. The combination with a disk playing phonograph having a turntable; of a record magazine adapted to receive double faced records, and a record carrying mechanism arranged to select a record from said magazine and place it on the turntable with a side selected by the carrying mechanism in playing position, and electro-magnetic means to reverse the action of said mechanism at a desired point in the playing of the record whereby to remove the record from the turntable and restore it to the cabinet.

74. The combination with a disk playing phonograph having a turntable; of a record magazine adapted to receive, double faced records, means operating to select a record from the magazine and place it on the turntable with a selected side uppermost, and electro-magnetic controlling mechanism operable to cause said means to remove and replace said record on the turntable with the sides reversed in position.

75. The combination with a disk playing phonograph having a turntable; of a record magazine adapted to receive double faced records, means operating to select a record from the magazine and place it on the turntable with a selected side uppermost, electro-magnetic controlling mechanism operable to cause said means to remove and replace said record on the turntable with the sides reversed in position, and other electro-magnetic controlling mechanism operable to cause restoration of the record to the cabinet in normal position.

76. The combination with a disk playing phonograph having a turntable; of a record magazine adapted to receive double faced records, means operating to select a record from the magazine and place it on the turntable with a selected side uppermost, and electro-magnetic controlling mechanism operable to cause said means to remove and replace said record on the turntable with the sides in the same position to effect repetition of the playing of the record.

77. The combination with a disk playing phonograph having a turntable; of a record magazine, means operating to select a record from the magazine and place it on the turntable, electro-magnetic controlling mechanism operable to cause said means to remove and replace said record on the turntable with the sides in the same position to effect repetition of the playing of the record, and other electro-magnetic controlling mechanism operable to cause restoration of the record to the cabinet in normal position.

78. The combination with a disk playing phonograph having a turntable; of a record magazine, means operating to select a record from the magazine and place it on the turntable, electro-magnetic controlling mecha-

nism operable to cause said means to remove and replace said record on the turntable with the sides reversed in position, and other electro-magnetic controlling mechanism operable to cause restoration of the record to the cabinet in normal position, at any time in the playing of the record at the will of the operator.

79. The combination with a disk playing phonograph having a turntable; of a record magazine, means operating to select a record from the magazine and place it on the turntable, and electro-magnetic controlling mechanism operable to cause said means to remove and replace said record on the turntable with the sides in the same position to effect repetition of the playing of the record, other electro-magnetic controlling mechanism operable to cause restoration of the record to the cabinet in normal position, at any time in the playing of the record at the will of the operator.

80. The combination with a disk playing phonograph having a turntable; of a record magazine, a record selector selectively positionable before said magazine, record handling mechanism controlled by the selector for taking a selected record from its magazine and delivering it to the turntable, and electro-magnetic control means for the handling mechanism operable to cause reverse action of the handling mechanism to restore the selected record to its place in the magazine.

81. The combination with a disk playing phonograph having a turntable; of a record magazine, a record selector selectively positionable before said magazine, record handling mechanism controlled by the selector for taking a selected record from its magazine and delivering it to the turntable, with a selected side in playing position, and electro-magnetic control means for the handling mechanism operable to cause reverse action of the handling mechanism to restore the selected record to its place in the magazine.

82. The combination with a disk playing phonograph having a turntable; of a record magazine, a record selector selectively positionable before said magazine, record handling mechanism controlled by the selector for taking a selected record from its magazine and delivering it to the turntable, with a selected side in playing position, electro-magnetic control means for the handling mechanism operable to cause reverse action of the handling mechanism to restore the selected record to its place in the magazine, and means to cause automatic actuation of said control means upon completion of the playing of the selected record.

83. The combination with a disk playing phonograph having a turntable; of a record magazine, a record selector selectively positionable before said magazine, record han-

a record, the record handling mechanism being released from the selector upon the latter being moved to record selecting position, electro-magnetic control means for the handling mechanism operable to cause the handling mechanism to effect repetition of the playing of the record prior to its restoration to the cabinet, means to cause actuation of said control means automatically upon completion of playing of the record the first time, and other electro-magnetic control means for said handling mechanism operable to cause the handling mechanism to remove the record from the turntable and replace it in the magazine in normal position.

90. The combination with a disk playing phonograph having a turntable; of a record magazine, a record selector selectively positionable before said magazine, record handling mechanism controlled by the selector for taking a selected record from its magazine and delivering it to the turntable, said selector and record handling mechanism being locked together to travel from normal position to position for selection of a record, the record handling mechanism being released from the selector upon the latter being moved to record selecting position, electro-magnetic control means for the handling mechanism operable to cause the handling mechanism to effect repetition of the playing of the record prior to its restoration to the cabinet, means to cause actuation of said control means automatically upon completion of playing of the record the first time, other electro-magnetic control means for said handling mechanism operable to cause the handling mechanism to remove the record from the turntable and replace it in the magazine in normal position, and means to cause actuation of said last control means automatically upon completion of the playing of the record the last time.

91. In an automatic phonograph having a magazine of records, electro-magnetically controlled selecting and playing mechanism for selecting a record from the magazine and playing a selected side thereof and subsequently returning the record to the magazine.

92. In an automatic phonograph having a magazine of records, an electro-magnetically controlled selecting and playing mechanism for selecting a series of records from the magazine, playing selected sides of each record and subsequently returning the records to normal positions in the magazine.

93. The combination with a disk playing phonograph having a turntable; of a record magazine, means operating to select a record from the magazine and place it on the turntable, electro-magnetic controlling mechanism operable to cause said means to remove and replace said record on the turntable with the sides reversed in position, and other electro-magnetic controlling mechanism operable

to cause restoration of the record to the cabinet in normal position.

94. The combination with a disk playing photograph having a turntable; of a pair of spaced record magazines, a record selector positionable between said magazines for selection of a predetermined record and including a guide, record handling mechanism controlled by the selector and movable to engage and be guided by said guide, means to control the guide to cause the handling mechanism to move into position in front of a selected magazine, and means to cause the handling mechanism to grasp the selected record and position the same for placing on the turntable.

95. The combination with a disk playing phonograph having a turntable; of a pair of spaced record magazines, a record selector positionable between said magazines for selection of a predetermined record and including a guide, record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, and means to reverse the action of the handling means to cause the same to grasp the record and again engage the guide to place the record in the magazine from which it was removed.

96. The combination with a disk playing phonograph having a turntable; of a pair of spaced record magazines, a record selector positionable between said magazines for selection of a predetermined record and including a guide, record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, with a selected side in playing position.

97. The combination with a disk playing phonograph having a turntable; of a pair of spaced record magazines, a record selector positionable between said magazines for selection of a predetermined record and including a guide, record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, with a selected side in playing position, and means to reverse the action of the handling means to cause the same to grasp the record and again engage the guide to place the rec-

ord in the magazine from which it was removed.

98. The combination with a disk playing phonograph having a turntable; of a pair of spaced record magazines, a record selector positionable between said magazines for selection of a predetermined record and including a guide, record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, means to lock the selector and handling means together during movement of the selector to record selecting position, and means to release the handling means from the selector upon the latter assuming record selection position.

99. The combination with a disk playing phonograph having a turntable; of a pair of spaced record magazines, a record selector positionable between said magazines for selection of a predetermined record and including a guide, a record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, means to reverse the action of the handling means to cause the same to grasp the record and again engage the guide to place the record in the magazine from which it was removed, means to lock the selector and handling means together during movement of the selector to record selecting position, and means to release the handling means from the selector upon the latter assuming record selection position.

100. The combination with a disk playing phonograph having a turntable; of a pair of spaced record magazines, a record selector positionable between said magazine for selection of a predetermined record and including a guide, record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, with a selected side in placing position, means to lock the selector and handling means together during movement of the selector to record selecting position, and means to release the handling means from the selector upon the latter assuming record selection position.

101. The combination with a disk playing phonograph having a turntable; of a pair of spaced record magazines, a record selector positionable between said magazines for selection of a predetermined record and including a guide, record handling mechanism controlled by the selector and movable to engage and be guided by said guide, means to control the guide to cause the handling mechanism to move into position in front of a selected magazine, means to cause the handling mechanism to grasp the selected record and position the same for placing on the turntable, with a selected side in playing position, means to reverse the action of the handling means to cause the same to grasp the record and again engage the guide to place the record in the magazine from which it was removed, means to lock the selector and handling means together during movement of the selector to record selecting position, and means to release the handling means from the selector upon the latter assuming record selection position.

In testimony whereof I affix my signature. 90
CHARLES V. KISSINGER.
